Application April 25, 1938, Serial No. 204,086

29 Claims. (Cl. 179—18)

The present invention relates to automatic telephone systems and has for one of its objects the provision of improved switching apparatus for use in setting up connections between the various lines of the system.

Automatic telephone systems conventionally comprise a plurality of subscriber lines provided with substations adapted to be connected thereto and an exchange housing switching apparatus including a plurality of subscriber controlled automatic switches adapted to be connected in tandem for setting up connections between the various subscriber lines. More particularly, the switching apparatus may include a group of finder switches and a group of connector switches having access to each subscriber line and groups of selector switches arranged between the groups of finder and connector switches and adapted to be connected thereto by trunk lines in order to forward the connection therebetween. Also, each subscriber line is provided with an individual line circuit for controlling the connections of the line to the finder and connector switches. Each line circuit and automatic switch embodies one or more relays provided with circuits including the conductors of the trunk lines, the circuits of the relays being selectively controlled in order to effect the desired operations of the line circuits and automatic switches. In a conventional telephone system of the type described, some of the control circuits of the various relays in the line circuits and automatic switches are so connected and arranged that potential difference is present between the contacts of the contact sets in the bank contacts of the automatic switches terminating the subscriber lines and the trunk lines even when the subscriber lines associated with the line circuits and the automatic switches are idle. Under certain operating conditions, it is desirable that no potential difference is present between the contacts of the contact sets in the bank contacts of the automatic switches, when the subscriber lines and automatic switches are idle.

In a telephone system of this type, an established connection between two substations is ordinarily cleared out and the apparatus involved in establishing the connection is released under the control of one or both of the parties at the substations upon the performance of release operations. In some instances, when the release operations are performed, all of the apparatus involved in establishing the connection is not immediately released under certain specific release conditions, due to the interaction between certain of the control relays embodied in the appa-

ratus. For example, it has been found that, following the performance of the release operations, the control relays do not always restore simultaneously or in the same sequence and, when the control relays restore in a predetermined sequence, an undesirable operating circuit for certain of the control relays is completed, which causes the relays to hunt. As a result of this hunting of the control relays, at least a portion of the apparatus involved in establishing the connection may be prevented from releasing properly.

It is an object of the present invention to provide an improved automatic telephone system of the type briefly described in which no potential difference is present between the contacts of the contact sets in the bank contacts of the automatic switches terminating idle subscriber lines and trunk lines extending to idle automatic switches.

Another object of the invention is to provide an improved automatic telephone system of the character noted which embodies an arrangement for positively preventing any interaction between the various control relays in the line circuits and automatic switches following the performance of a release operation at a substation to clear out an established connection, thereby to prevent the operated switching apparatus from being held operated.

A further object of the invention is to provide in an automatic telephone system of the type noted an improved line circuit which is connected and arranged to prevent the presence of potential between the contacts of the contact sets in the bank contacts of the finder and connector switches terminating the associated subscriber line when the subscriber line is idle.

A further object of the invention is to provide in an automatic telephone system of the type noted an improved automatic switch which is constructed and arranged to prevent the presence of potential between the contacts of the contact sets in the bank contacts of the preceding automatic switches having access to the automatic switch when the automatic switch is idle.

A further object of the invention is to provide in an automatic telephone system of the type noted an improved line circuit which is connected and arranged positively to prevent interaction between the control relays therein and the control relays in the automatic switches involved in an established connection following the performance of a release operation to clear out the established connection.

A further object of the invention is to provide in an automatic telephone system of the type

noted an improved automatic switch which is connected and arranged positively to prevent interaction between the control relays therein and the control relays in the line circuits involved in an 5 established connection following the performance of a release operation to clear out the established connection.

The features of the present invention are illustrated as being incorporated in an exchange 10 having a capacity of ten thousand lines and including groups of finder, first selector, second selector and connector switches. The various lines individually terminate in line circuits for controlling the connections of the lines to the 15 finder and connector switches. In accordance with one feature of the invention, each subscriber line is normally disconnected from the associated link and connecting lines terminating, respectively, at the bank contacts of groups of 20 finder and connector switches and is connected thereto only when the subscriber line is busy, thereby to prevent the presence of potential between the contacts of the contact sets in the bank contacts of the finder and connector switches 25 respectively terminating the link and connecting lines associated with the subscriber line, when the subscriber line is idle. More specifically, the associated subscriber, link and connecting lines each comprise two line conductors, the line 30 conductors of the connecting line being directly connected to the corresponding line conductors of the link line, and the line conductors of the subscriber line being connected to the corresponding line conductors of the link line when the subscriber 35 line is busy. In one form of the improved line circuit, one of the line conductors of the subscriber line is directly connected to a corresponding one of the line conductors of the link line, while the other line conductor of the 40 subscriber line is connected to the other line conductor of the link line under the control of a combined line and cut-off relay. In another form of the improved line circuit, both of the line conductors of the subscriber line are normally 45 disconnected from the corresponding line conductors of the link line and are connected thereto under the control of a cut-off relay.

In accordance with another feature of the invention, both forms of the line circuit are provided with means for preventing the interaction of a certain control relay therein and a certain control relay provided in at least one of the selector switches, following the performance of a switch train release operation performed at 50 a substation connected to a calling line, which interaction, if allowed to occur, is effective to prevent the immediate release of the corresponding line circuit and selector switch. More specifically, each of the line circuits embodies 55 contacts controlled by a relay embodied therein and operative in response to the performance of a release operation at a substation connected to a calling line, which contacts interrupt an undesirable operating circuit for the relays 60 noted, thereby to prevent the interaction of the relays.

In accordance with a further feature of the invention, each of the second selector and connector switches is provided with means for preventing the presence of a potential between the contacts of the contact sets in the bank contacts of the preceding selector switches. This is accomplished by providing in each of the second selector and connector switches a relay 70 operative to initiate operation of the switch,

which relay is provided with an operating circuit including one terminal of a source of supply derived in the switch, a series connection between the line and control conductors of a trunk line incoming to the switch and the other terminal of the source of supply derived in a preceding switch having access to the switch, where- 5 by no potential is present between the conductors of the trunk line incoming to the selector or connector switch until after the trunk line 10 is seized by the preceding switch.

In accordance with a further feature of the invention, each of the second selector switches is provided with means for preventing interaction between a certain control relay provided therein and one of the relays provided in one of the line circuits associated respectively with two connected lines following the performance of a release operation at the substation connected to the calling one of the lines, which interaction, as previously noted, is effective to prevent the immediate release of the corresponding line circuit and selector switch. In two different forms of the second selector switch, this is accomplished by providing a set of contact springs in the previously noted undesirable operating circuit, which contact springs are controlled to interrupt the undesirable operating circuit by a predetermined operation of the wiper operating mechanism embodied in the switch, the predetermined operation of the mechanism being incident to the performance of the release operations. In a third form of the selector switch an uni-directional conducting device in the form of a copper oxide rectifier is included in the undesirable operating circuit, which device blocks the flow of current through the undesirable operating circuit, thereby to cause the restoration 30 of the control relays noted and the consequent 35 release of the corresponding line circuit and selector switch.

Further features of the invention pertain to the particular arrangement of the circuit elements, whereby the above-outlined and additional operating features are attained. 40

The novel features believed to be characteristic of the invention are set forth with particularity in the appended claims. The invention, both as to its organization and method of operation, together with further objects and advantages thereof, will best be understood by reference to the following specification, taken in connection with the accompanying drawings, in which Figure 8 illustrates the general arrangement of an automatic telephone system having 55 incorporated therein apparatus constructed and arranged in accordance with the present invention; Figs. 1, 2 and 3, taken together, illustrate the details of the automatic telephone system of Fig. 8; Fig. 4 illustrates a modified form of the selector switch of Fig. 2; Fig. 5 illustrates another modified form of the selector switch of Fig. 2; Fig. 6 illustrates a further modified form of the selector switch of Fig. 2; and Fig. 7 illustrates a modified form of the line circuit of Fig. 1. 60 65

Referring now more particularly to Fig. 8 of the drawings, there is illustrated the general arrangement of the telephone system shwn in Figs. 1, 2 and 3. In brief, the system of Fig. 8 comprises an exchange having extending thereto a 70 plurality of subscriber lines, two of which are indicated at 101 and 109, and a plurality of subscriber controlled automatic switches adapted to be connected in tandem and including a line 75 finder switch 182, a first selector switch 100, a

second selector switch 200 and a final selector or connector switch 300, for setting up connections between the various subscriber lines. It will be understood that a plurality of switches of each type, namely, a plurality of line finder switches, a plurality of first selector switches, a plurality of second selector switches, and a plurality of final selector or connector switches, are provided in the system for performing the usual line switching functions. The switches of each type are respectively arranged in groups and, in accordance with universally followed practice, the number of switches in each group is determined in accordance with the maximum volume of traffic the particular switch group is required to handle. Specifically, the exchange is designed to serve ten thousand subscriber lines, these lines being divided into one hundred-line groups with the conductors of the lines of each group terminating in the bank contacts of a group of finder switches and a group of connector switches. In accordance with conventional practice, each line is multiplied between the corresponding bank contacts of a group of finder switches and the corresponding bank contacts of a group of connector switches, whereby a plurality of such switches are available for setting up connections between each line and every other line of the system. Thus, the conductors of the line 101 are adapted to be connected by way of a line circuit 180 to the bank contacts of the finder switch 182, which is one of a group of finder switches for serving the group of lines including the line 101. This line, in addition to being multiplied in the bank contacts of the finder switches in the group noted, is also multiplied in the bank contacts of a group of connector switches. Similarly, the line 109 is adapted to be connected by way of a line circuit 181 to the bank contacts of the connector switch 300, and is multiplied between the corresponding contacts of other connector switches of the group of connector switches including the connector switch 300 and the corresponding bank contacts of the group of finder switches including the finder switch 182.

The end of each subscriber line remote from the exchange housing the switching apparatus illustrated terminates in a subscriber substation which may be of any desired arrangement. Two such substations are diagrammatically illustrated at A and B associated with the lines 101 and 109, respectively. In brief, each of the substations may comprise the usual hand set type of transmitter and receiver, a hook switch, a ringer, and an impulsive device for transmitting the switch control impulses by way of the associated line to the automatic switching equipment embodied in the line terminating exchange.

As indicated above, each subscriber line has associated therewith a group of line finder switches, any one of which is capable of establishing a link connection between the subscriber line and an associated first selector switch, each finder switch and its associated first selector switch constituting a finder-selector link. In order, therefore, to assign the finder-selector links constituting a particular group to successive calling subscriber lines included in the associated line group, there are provided distributors, associated with the group of finder switches including the switch 182 associated with the first selector switch 100 being indicated generally at 183. Since this distributor may be of any conventional arrangement, it has been only diagrammatically illustrated in the drawings.

Each of the line finder, first selector, second selector, and connector switches is preferably of the well-known Strowger type having embodied therein a wiper carriage structure adapted to be translated vertically to bring the wipers thereof opposite a particular level of bank contacts, and then rotated to bring the contacts into engagement with a particular set of contacts in a selected level; vertical, rotary and release magnets; and control relays suitably connected and arranged to control the energization of the various magnets and the line switching in accordance with particular functions of the switch. Obviously, the particular arrangement of the control apparatus as embodied in the switches of different type is different in each instance, depending upon the character of the switch, as is more fully explained subsequently. Since the finder switches are of conventional construction and well understood, the finder switch 182 has been only diagrammatically illustrated.

Each of the line circuits comprises a combined line and cut-off relay of the two-step type, two of which are shown at R170 and R165 as being respectively embodied in the line circuits 180 and 181. Each of the first selector switches included in the system may be identical with that indicated generally at 100 in Fig. 1. In brief, this switch comprises a switching mechanism, indicated at 129, of the well-known Strowger type including a plurality of bank contacts arranged in levels; wipers for engaging the bank contacts; means comprising a vertical operating magnet M184 for stepping the wiper carriage structure vertically to position the wipers opposite a particular selected level; means comprising a rotary operating magnet M185 for imparting rotary motion to the wiper carriage structure, thereby to move the wipers into engagement with a selected contact set in the selected level; and means comprising a release magnet M186 for restoring the wiper carriage structure to its normal position during the release of the switch. Also incorporated in the selector switch 100 are the usual line and hold relays R120 and R130, respectively, a switching through relay R150, circuit controlling relays R140 and R160, and rotary and vertical off-normal springs indicated respectively at 187 and 197.

Each of the second selector switches included in the system may be identical with that indicated generally at 200 in Fig. 2. In general, this switch is of the same construction as the first selector switch 100 and comprises a switching mechanism, indicated at 218, of the well-known Strowger type including a plurality of bank contacts arranged in levels; a carriage structure provided with wipers for engaging the bank contacts; means comprising a vertical operating magnet M260 and a rotary operating magnet M261 for imparting the respective movements to the wiper carriage structure embodied in the switching mechanism; and means comprising a release magnet M262 for restoring the wiper carriage structure to its normal position during the release of the switch. Also incorporated in the selector switch 200 are the usual line and hold relays R210 and R220, respectively, a switching through relay R240, circuit controlling relays R230 and R250, and rotary and vertical off-normal springs indicated respectively at 263 and 269.

Each of the final selector or connector switches included in the system may be identical with that indicated generally at 300 in Fig. 3. In

brief, this switch comprises a switching mechanism indicated at 399 of the well-known Strowger type including a plurality of bank contacts arranged in levels; a carriage structure provided with wipers for engaging the bank contacts; means comprising a vertical operating magnet M390 for stepping the wiper carriage structure vertically to position the wipers opposite a particular selected level; means comprising a rotary operating magnet M391 for imparting rotary motion to the wiper carriage structure, thereby to move the wipers into engagement with a selected contact set in the selected level; and means comprising a release magnet M392 for restoring the wiper carriage structure to its normal position during the release of the switch. Also incorporated in the connector switch 300 are the usual line, hold and battery reversing relays R320, R330 and R340, respectively, a ring cut-off relay R350, a busy relay R360, a switching through relay R380, circuit controlling relays R340 and R370 and two sets of vertical off-normal springs indicated at 385 and 393.

25 Referring now more particularly to the operation of the apparatus illustrated in Figs. 1, 2 and 3, when a subscriber, such, for example, as the subscriber at the substation A, initiates a call over the line 101 to a second subscriber substation, such, for example, as the substation B, by lifting his receiver from its hook, a circuit is completed for energizing in series the three windings of the combined line and cut-off relay R170. This circuit extends from ground at the upper 35 terminal of the lower winding of R170 by way of the lower winding of R170, RA172, the line conductor C103 of the line 101, the bridge across C103 and C102 at the substation A, C102, RA171, the upper winding of R170, the control conductor C107, and the intermediate winding of R170 to battery. Due to the high series resistance of this circuit, the relay R170 only partially operates to close the "X" contacts associated respectively with RA174 and RA175. At RA175, 40 ground potential at RA176 is applied to the distributor start conductor C176, thereby to cause the distributor 183 to initiate the operation of one of the finder switches to search for the calling line 101. At RA174 a path is prepared for applying ground potential to the control conductor C107 of the line 101, thereby to mark the line 101 as busy in the bank contacts of the connector switches at which this line terminates. Battery potential as applied to the lower terminal of the 45 intermediate winding of R170 is also extended by way of RA174 to the control conductor C105 terminating in the bank contacts of the finder switches, thereby to mark the line 101 as the calling line. It is noted that the distributor 183 preferably functions in a manner such that an 50 idle line finder switch is conditioned immediately to start operating in search of a calling line upon the application of ground potential to the start conductor C176. Assuming, for example, that 55 the finder switch 182 is the switch assigned by the distributor 183 to the use of the calling line 101, the wipers of this switch are first operated to a position opposite the level in which the calling line is terminated, this level being identified through the application of marking or ground potential to the start conductor C176. When this level is found, the wipers are automatically stepped into the bank contact field to 60 test the individual lines terminating at the contact sets of the selected bank contact level.

When the calling line, as marked by the application of battery to the control conductor C105 thereof is found, the hunting operation is automatically discontinued and the control apparatus embodied in the finder switch 182 functions automatically to switch the calling line through and establish a connection between this line and the trunk line 124 incoming to the first selector switch 100. Following this operation, the line 65 finder switch 182 is marked as busy in the distributor 183 and the distributor is started in operation to a position corresponding to the next available idle line finder switch. Also in the course of these operations, direct ground potential is applied in the finder switch 182 to the control conductor C105, thereby to mark the calling line as busy through the application of ground potential to the control conductor C107 of the line 101 and to cause the full energization 70 of the intermediate winding of R170. As a result, the relay R170 now fully operates to remove, at RA176, ground potential from the start conductor C176 and to disconnect its windings from the line conductors C102 and C103 of the line 101. Thus, the calling line is cleared of any impedance elements which might interfere with the transmission of impulsing and voice frequency currents. Also, upon fully operating, the relay R170 completes, at RA173, a connection between the line conductor C103 of the line 75 101 terminating at the substation A and the line conductor C104 of the line 101 terminating in the bank contacts of the finder switch 182, thereby to complete a link connection between the substation A and the first selector switch 100. The line comprising the conductors C102, C104 and C105 and terminating in the bank contacts of the finder switch 182 also constitutes a link line. If desired, both of the line conductors C102 and C104 may be normally disconnected from 80 the line conductors C102 and C103 of the subscriber line 101 and connected thereto by the relay R170, as pointed out in connection with the modified form of line circuit 709 of Fig. 7. 85 Immediately the link connection is established 85 between the substation A and the first selector switch 100, a circuit is completed for energizing the line relay R120 embodied in this switch. This circuit extends from ground on the dial tone conductor C138 by way of the contact springs 191 and 192 of the rotary off-normal springs 187, the lower winding of R120, RC159', RA158, the line conductor C127 of the trunk line 124, the finder switch 182, C104, RA173, C103, the bridge across C103 and C102 at the substation A, C102, the 90 finder switch 182, C125, RA151, RC152 and the upper winding of R120 to battery. Dial tone current is conducted over a similar path to that just traced and through the receiver of the telephone instrument at the substation A, thereby 95 to indicate to the calling party that the dialing operations may be performed. Upon operating, the line relay R120 completes, at RA121 and RC122, a circuit for energizing the hold relay R130, this circuit extending from ground at RA157 by way of RA121, RC122 and the winding of R130 to battery. The last-mentioned relay, in turn, operates to complete, at RA131, an obvious path for applying multiple ground potential to the release conductor C126 of the trunk line 100 124, thereby to hold the finder switch 182 operated and to retain ground potential upon the control conductor C107 of the calling line 101 after ground potential in the finder switch 182 is removed. This ground potential applied to 105

the release conductor C126 also retains the relay R170 of the line circuit 180 in operated position. At RA132 and RC133, an impulsing circuit is prepared for energizing in series the control relay R140 and the vertical magnet M184 in accordance with the impulses comprising the first digit dialed at the calling substation A.

The impulsing circuit for the control relay R140 and the vertical magnet M184 is completed at the beginning of the first impulse of the first series of impulses dialed at the calling substation A and when the line relay R120 restores. This circuit extends from ground at RA157 by way of RA121, RC123, RA132, RC133, the winding of R140 and the winding of M184 to battery. When energized over the above-traced circuit, the vertical magnet M184 lifts the wiper carriage structure of the mechanism 129 one step or to a position opposite the first level of bank contacts. Upon operating, the control relay R140 prepares at RA141 and RA142 a circuit, traced hereinafter, for energizing the control relay R160 and interrupts at RA142 and RC143 a point in the circuit for energizing the rotary magnet M185. Simultaneously with this operation, the vertical off-normal springs 197 are operated to the off-normal position, thereby completing at the contact springs 193 and 194 the circuit for energizing the control relay R160, this circuit extending from ground at RA131 by way of RA142, RA141, the contact springs 193 and 194 and the winding of R160 to battery. At the contact springs 195 and 196 of the vertical off-normal springs 197, a circuit traced hereinafter, is prepared for energizing the release magnet M186. During each impulse of the first series of impulses, the vertical magnet M184 is energized in the above-described manner so that, at the conclusion of the first digit, the wiper carriage structure of the mechanism 129 stands in a position opposite the level of bank contacts terminating the group of trunks outgoing to the second selector switches having access to the connector switches at which the called line 109 terminates. During the first series of impulses, each time the bridge across the line conductors C102 and C103 at the substation A is interrupted, the line relay R120 restores, causing the control relay R140 and the vertical magnet M184 to be energized, as previously explained. Also, each time the bridge across the line conductors C102 and C103 at the substation A is completed, the line relay R120 reoperates and completes the circuit for energizing the hold relay R130. Thus, the hold relay R130 and the control relay R140 remain operated during the impulsing period, due to their slow-to-release characteristics. Upon operating, the control relay R160 prepares at RA161 a point in the circuit for energizing the rotary magnet M185 and completes at RA162 a locking circuit for itself, the latter circuit extending from ground at RA157 by way of RA162, the contacts controlled by the armature 185' of the rotary magnet M185, the contact springs 193 and 194 and the winding of R160 to battery. With the wiper carriage structure of the switching mechanism 129 standing opposite the level of bank contacts terminating the group of trunks leading to the respective second selector switches of the group including the second selector switch 200, the first selector switch 100 is automatically conditioned to search for an idle one of these trunks. Thus, shortly following the end of the first series of impulses, the control relay R140 restores to interrupt, at RA141 and RA142, the original operating circuit of the control relay

R160 and to complete, at RA142 and RC143, the circuit for energizing the rotary magnet M185, the latter circuit extending from ground at RA131 by way of RA142, RC143, RA161 and the winding of M185 to battery. Upon being energized over the above-traced circuit, the rotary magnet M185 steps the wipers of the mechanism 129 into engagement with the first set of contacts in the selected level and simultaneously interrupts, at 185', the locking circuit of the control relay R160, which latter relay restores to interrupt, at RA161, the operating circuit of the rotary magnet M185 and, at RA162, a further point in its locking circuit. When the rotary magnet M185 restores, it prepares a point, at 185', in a circuit for testing the idle or busy condition of the trunk line terminating at the engaged first set of contacts in the selected level. If this first trunk line is busy, ground potential appears upon the release conductor thereof, thereby causing the control relay R160 to be reoperated, this circuit extending from the grounded release conductor by way of the conductor C136, RA154, RC155, the armature 185', the contact springs 193 and 194 and the winding of R160 to battery. It is noted that the ground potential appearing upon the conductor C136 and extending by way of RA154 and RC155 to the upper terminal of the switching through relay R150 causes this relay to be short-circuited, since the lower terminal of the winding thereof is connected by way of the contact springs 189 and 188 of the rotary off-normal springs 187 to the grounded release conductor C126. Thus, operation of this relay is prevented. Upon reoperating, the control relay R160 completes, at RA161 the circuit for energizing the rotary magnet M185 and completes, at RA162, its locking circuit. Upon operating, the rotary magnet M185 steps the wipers of the mechanism 129 into engagement with the second set of contacts in the selected level and simultaneously interrupts at 185' the locking circuit of the control relay R160, whereupon R160 restores and interrupts, at RA161, the operating circuit of the rotary magnet M185 and interrupts, at RA162, a further point in its locking circuit. The rotary magnet M185 then restores and completes, at 185', the circuit for testing the idle or busy condition of the trunk line terminating at the second set of contacts in the selected level. If the second trunk is busy, ground potential appears upon the release conductor thereof, causing the control relay R160 to be reoperated, as previously explained, in order to cause the rotary magnet M185 to be reoperated, thereby stepping the wipers of the mechanism 129 into engagement with the third set of contacts in the selected level. Thus, the rotary magnet M185 operates to rotate the wipers of the mechanism 129 step by step over the contact sets in the selected level until they are moved into engagement with a trunk line extending to an idle second selector switch.

Assuming that the second selector switch 200 is the first idle selector switch in the selected level, when the wipers of the mechanism 129 engage the set of contacts terminating the trunk line 214 extending to the switch 200, further operation of the rotary magnet M185 is interrupted, as no potential whatever appears upon the release conductor C216 of the trunk line 214. Thus, the switching through relay R150 is not short-circuited but is energized in series with the control relay R160, this circuit extending from the grounded release conductor C126 by way of

the contact springs 188 and 189, the winding of R150, the armature 185', the contact springs 193 and 194, and the winding of R160 to battery. When the switching through relay R150 is energized over the above-traced circuit, it is operated; while the control relay R160, which is of the marginal type, is not operated, due to the high series resistance of this circuit. Upon operating, the switching through relay R150 connects the line conductors C125 and C127 of the trunk line 124 to the line conductors C135 and C137, respectively, and connects the release conductor C126 of the trunk line 124 to the conductor C136. At this time, the trunk line 124 extending to the first selector switch 100 is connected through this switch to the trunk line 214 extending to the second selector switch 200; the line conductor C125 being connected by way of RA151, RC153, C135, the wiper 117 and the contact 144 to the line conductor C215; the line conductor C127 being connected by way of RA158, RC159, C137, the wiper 119 and the contact 146 to the line conductor C217; and the release conductor C126 being connected by way of RC156, RA154, C136, the wiper 118 and the contact 145 to the release conductor C216.

Also, upon operating, the switching through relay R150 interrupts, at RA151 and RC152 and at RA158 and RC159' the operating circuit of the line relay R120, thereby interrupting the path for transmitting dial tone to the receiver of the telephone instrument at the substation A. At RA151, the relay R150 interrupts the operating circuit of the hold relay R130, and, at RA157, it interrupts a point in the circuit for energizing the release magnet M186. When the line relay R120 restores, it interrupts, at RA121 and RC122, a further point in the operating circuit of the hold relay R130 and prepares, at RA121 and RC123, a point in the circuit for energizing the release magnet M186. Shortly thereafter, the hold relay R130 restores and interrupts, at RA132 and RC133, a further point in the circuit for energizing in series the control relay R140 and the vertical magnet M184, and prepares, at RA132 and RC134, a further point in the circuit for energizing the release magnet M186. Also, upon restoring, the hold relay R130 removes ground potential at RA131 from the release conductor C126, rendering the release of the switch train including the operated first selector switch 100 under the control of the second selector switch 200, ground being retained upon the release conductor C216 in the second selector switch 200 at this time in a manner more fully described subsequently. The switching through relay R150 in the first selector switch 100, the finder switch 182, and the relay R170 in the line circuit 180 are retained in operated positions at this time by virtue of completed circuits including the grounded release conductor C216.

In the event all of the trunk lines terminating at the selected level of bank contacts lead to busy second selector switches, the rotary magnet 129 M185 will cause the wipers of the mechanism 129 to be stepped to their respective eleventh off-normal positions, at which time the rotary off-normal springs 187 are moved to the off-normal position. When this occurs, the circuit for energizing the switching through relay R150 in series with the control relay R160 is interrupted at the contact springs 188 and 189 in order to prevent operation of R150, and the wiper 118 connected to the conductor C136 disengages the contact in the tenth contact set having ground potential

thereon, in order to prevent reoperation of the control relay R160 and the consequent rotation of the wipers into a further position by the rotary magnet M185. Also, at the contact springs 191 and 192, dial tone is removed from the loop extending to the receiver of the telephone instrument at the substation A, while, at the contact springs 190 and 192 of the rotary off-normal springs 187, busy tone current is returned to the receiver of the telephone instrument at the substation A. This circuit extends from the grounded winding of a busy tone current transformer, not shown, to the busy tone conductor C139, and by way of the contact springs 190 and 192, the lower winding of R120, RC159', RA158, C127, the finder switch 182, and through the receiver of the telephone instrument included in the bridge across the calling line 101, the finder switch 182, C125, RA151, RC152 and the upper winding of R120 to grounded battery. The resulting busy tone indicates to the calling subscriber that the desired connection can not immediately be completed.

The calling subscriber, upon receiving busy tone, may initiate the release of the operated switch train by restoring his receiver to its hook to open the loop circuit over which the line relay R120 is held operated. This relay, upon restoring, interrupts, at RA121 and RC122, the operating circuit of the hold relay R130 and prepares, at RA121 and RC123, a point in the circuit for energizing the release magnet M186. Shortly thereafter, the hold relay R130 restores and removes ground potential, at RA131 from the release conductor C126, whereupon the operated finder switch 182 is restored to its idle position and the operated relay R170 in the line circuit 180 is restored to its idle position. Also, upon restoring, the hold relay R130 completes at RA132 and RC134 the circuit for energizing the release magnet M186, this circuit extending from ground at RA151 by way of RA121, RC123, RA132, RC134, the contact springs 195 and 196 of the vertical off-normal springs 187 and the winding of M186 to battery. In response to the energization of the release magnet M186, the wipers of the mechanism 129 are restored to normal, at which time the rotary and vertical off-normal springs 187 and 191, respectively, are returned to normal. Thus, the partially completed connection is cleared out and the switches involved therein are released for further use.

Continuing now with the operation of the apparatus to establish a connection to the called line 109 and assuming that the second selector switch 200 is selected by the first selector switch 100 to forward the connection, immediately the loop circuit is extended to the second selector switch 200, the line relay R210 in this switch is energized. This circuit extends from the grounded release conductor C126 by way of RC156, RA154, C136, the wiper 118, the contact 145, the release conductor C216, the contact spring 264 of the rotary off-normal springs 263, the contact springs 274 and 275 of the vertical off-normal springs 269, the contact springs 267 and 268 of the rotary off-normal springs 263, the lower winding of R210, RC249', RA248, the line conductor C217 of the trunk line 214, the operated first selector switch 100, the operated finder switch 182, the bridge at the substation A across the line 101, the operated finder switch 182, the operated first selector switch 100, the line conductor C215 of the trunk line 214, RA241, RC242 and the upper winding of R210 to battery. Upon

- operating, the line relay **R210** completes, at RA211 and RC212, an obvious circuit for energizing the hold relay **R220**, this circuit extending from ground at RA247 by way of RA211, RC212 and the winding of **R220** to battery. The last-mentioned relay in turn operates to complete, at RA221, an obvious path for applying multiple ground potential to the release conductor **C216** of the trunk line 214, thereby to hold the first selector switch 100 and the finder switch 182 operated and to retain ground potential upon the control conductor **C107** of the calling line 101 after the hold relay **R130** in the first selector switch 100 restores to remove ground at RA131 from the release conductor **C126** as previously explained. This ground potential applied to the release conductor **C216** also retains the relay **R170** in the line circuit 180 in operated position. At RA222 and RC223, an impulsive circuit is prepared for energizing in series the control relay **R230** and the vertical magnet **M260** in accordance with the impulses comprising the second digit dialed at the calling substation A. Also, the hold relay **R220** completes, at RA225, a path for short-circuiting the contact springs 274 and 275, thereby rendering the energization of the line relay **R210** under the control of the grounded release conductor **C216** and independent of the vertical off-normal springs 269.
- The impulsive circuit for the control relay **R230** and the vertical operating magnet **M260** is completed at the beginning of the first impulse of the second series of impulses dialed at the calling substation A and when the line relay **R210** restores, this circuit extending from ground at RA247 by way of RA211, RC213, RA222, RC223, the winding of **R230** and the winding of **M260** to battery. When energized over the above-traced circuit, the vertical magnet **M260** lifts the wiper carriage structure of the mechanism 218 one step or to a position opposite the first level of bank contacts. Upon operating, the control relay **R230** prepares at RA231 and RA233 a circuit, traced hereinafter, for energizing the control relay **R250** and interrupts at RA233 and RC234 a point in the circuit for energizing the rotary magnet **M261**. Simultaneously with this operation, the vertical off-normal springs 269 are operated to the off-normal position, thereby completing at the contact springs 270 and 271 the circuit for energizing the control relay **R250**, this circuit extending from ground at RA221 by way of RA233, RA231, the contact springs 270 and 271 and the winding of **R250** to battery. At the contact springs 272 and 273 of the vertical off-normal springs 269, a circuit, traced hereinafter for energizing the release magnet **M262** is prepared, and the contact springs 274 and 275, short-circuited by the armature RA255 of the hold relay **R220**, are moved out of contact with each other. During each impulse of the second series of impulses, the vertical magnet **M260** is energized in the above-described manner so that, at the conclusion of the second digit, the wiper carriage structure of the mechanism 218 stands in a position opposite the level of bank contacts terminating the group of trunks outgoing to the final selector or connector switches at which the called line 109 terminates. During the second series of impulses, each time the bridge across the line conductors **C102** and **C103** at the substation A is interrupted, the line relay **R210** restores, causing the control relay **R230** and the vertical magnet **M260** to be energized, as previously explained. Also, each time the bridge across the line conductors **C102** and **C103** at the substation A is completed, the line relay **R210** reoperates and completes the energizing circuit of the hold relay **R220**. Thus, the hold relay **R220** and the control relay **R230** remain operated during the impulsive period, due to their slow-to-release characteristic. Upon operating, the control relay **R250** prepares at RA251 a point in the circuit for energizing the rotary magnet **M261** and completes at RA252 a locking circuit for itself, the latter circuit extending from ground at RA247 by way of RA252, the contacts controlled by the armature 261' of the rotary magnet **M261**, the contact springs 270 and 271 and the winding of **R250** to battery.
- With the wiper carriage structure of the switching mechanism 218 standing opposite the level of bank contacts terminating the group of trunk lines leading to the respective final selector or connector switches of the group including the final selector or connector switch 300, the second selector switch 200 is automatically conditioned to search for an idle one of these trunk lines. Thus, shortly following the end of the second series of impulses, the control relay **R230** restores to interrupt, at RA231 and RA233, the original operating circuit of the control relay **R250** and to complete, at RA233 and RC234, the circuit for energizing the rotary magnet **M261**, the latter circuit extending from ground at RA221 by way of RA233, RC234, RA251 and the winding of **M261** to battery. Upon being energized over the above-traced circuit, the rotary magnet **M261** steps the wipers of the mechanism 218 into engagement with the first set of contacts in the selected level and simultaneously interrupts, at 261', the locking circuit of the control relay **R250**, which latter relay restores and interrupts, at RA251, the operating circuit of the rotary magnet **M261** and interrupts, at RA252, a further point in its locking circuit. When the rotary magnet **M261** restores, it prepares a point, at 261', in a circuit for testing the idle or busy condition of the trunk line terminating at the engaged first set of contacts in the selected level. If this first trunk line is busy, ground potential appears upon the release conductor thereof, thereby causing the control relay **R250** to be reoperated over a circuit extending from the grounded release conductor by way of the conductor **C291**, RA244, RC245, 261', the contact springs 270 and 271 and the winding of **R250** to battery. It is noted that the ground potential appearing upon the conductor **C291** and extending by way of RA244 and RC245 to the upper terminal of the switching-through relay **R240** causes this relay to be short-circuited, as the lower terminal of the winding thereof is connected by way of the contact springs 265 and 254 of the rotary off-normal springs 263 to the grounded release conductor **C216**, thereby preventing operation of this relay. Upon reoperating, the control relay **R250** completes, at RA251 the circuit for energizing the rotary magnet **M261** and completes, at RA252, its locking circuit. Upon operating, the rotary magnet **M261** steps the wipers of the mechanism 218 into engagement with the second set of contacts in the selected level and simultaneously interrupts at 261' the locking circuit of the control relay **R250**, whereupon **R250** restores and interrupts, at RA251, the operating circuit of the rotary magnet **M261** and interrupts, at RA252, a further point in its locking circuit. The rotary magnet **M261** then restores and completes, at 261', the

circuit for testing the idle or busy condition of the trunk line terminating at the second set of contacts in the selected level. If the second trunk is busy, ground potential appears upon the release conductor thereof, causing the control relay R250 to be reoperated, as previously explained, in order to cause the rotary magnet M261 to be reoperated, thereby stepping the wipers of the mechanism 218 into engagement with the third set of contacts in the selected level. Thus, the rotary magnet M261 operates to rotate the wipers of the mechanism 218 step by step over the contact sets in the selected level until they are moved into engagement with a trunk line extending to an idle connector switch.

Assuming that the connector switch 300 is the first idle connector switch in the selected level, when the wipers of the mechanism 218 engage the set of contacts terminating the trunk line 295 extending to the connector switch 300, further operation of the rotary magnet M261 is interrupted, as no potential whatever appears upon the release conductor C297 of the trunk line 295. Thus, the switching through relay R240 is not short-circuited but is energized in series with the control relay R250 over a circuit extending from the grounded release conductor C216 by way of the contact springs 264 and 265, the winding of R240, 261', the contact springs 270 and 271, and the winding of R250 to battery. When the switching through relay R240 is energized over the above-traced circuit, it is operated; while the control relay R250, which is of the marginal type, is not operated, due to the high series resistance of this circuit. Upon operating, the switching-through relay R240 connects the line conductors C215 and C217 of the trunk line 214 to the conductors C290 and C292, respectively, and connects the release conductor C216 of the trunk line 214 to the conductor C291. At this time the trunk line 214 extending to the second selector switch 200 is connected through the selector switch 200 to the trunk line 295 extending to the connector switch 300; the line conductor C215 being connected by way of RA241, RC243, C290, the wiper 276 and the contact 280 to the line conductor C296; the conductor C217 being connected by way of RA248, RC249, C292, the wiper 279 and the contact 282 to the line conductor C298; and the release conductor C216 being connected by way of RC246, RA244, C291, the wiper 277 and the contact 281 to the release conductor C297.

Also, upon operating, the switching-through relay R240 interrupts, at RA241 and RC242 and at RA248 and RC249', the operating circuit of the line relay R210. At RA247, the relay R240 interrupts the operating circuit of the hold relay R220 and, at RA247, it interrupts a point in the circuit for energizing the release magnet M262. When the line relay R210 restores, it interrupts, at RA211 and RC212, a further point in the operating circuit of the hold relay R220 and prepares, at RA211 and RC213, a point in the circuit for energizing the release magnet M262. Shortly thereafter, the hold relay R220 restores and removes ground potential, at RA221, from the release conductor C216, whereupon the first selector switch 100 and the operated finder switch 182 are restored to their idle positions and the operated relay R170 in the line circuit 180 is restored to its idle position. Also, upon restoring, the hold relay R220 completes, at RA222 and RC224, the circuit for energizing the release magnet M262, this circuit extending from ground at RA247 by way of RA211, RC213, RA222, RC224, the contact springs 272 and 273 of the vertical off-normal springs 269 and the winding of M262 to battery. In response to the energization of the release magnet M262, the wipers of the mechanism 218 are restored to normal, at which time the rotary and vertical off-normal springs 263 and 269, respectively, are returned to normal. Thus, the partially completed connec-

operated second selector switch 200 under the control of the connector switch 300, ground being retained upon the release conductor C297 in the connector switch 300 at this time in a manner more fully described subsequently. The switching through relays R150 and R240 in the first and second selector switches 100 and 200, respectively, the finder switch 182, and the relay R170 in the line circuit 180 are retained in operated positions at this time by virtue of completed circuits including the grounded release conductor C297.

In the event all of the trunks terminating at the selected level of bank contacts lead to busy connector switches, the rotary magnet M261 will cause the wipers of the mechanism 218 to be stepped to their respective eleventh off-normal positions, at which time the rotary off-normal springs 263 are moved to the off-normal position. When this occurs, the circuit for energizing the switching through relay R240 in series with the control relay R250 is interrupted at the contact springs 264 and 265, in order to prevent operation of R240, and the wiper 277 connected to the conductor C291 disengages the contact in the tenth contact set having ground potential thereon in order to prevent reoperation of the control relay R250 and the consequent rotation of the wipers into a further position by the rotary magnet M261. At the contact springs 266 and 268 of the rotary off-normal springs 263, a path is completed for returning busy tone current to the receiver of the telephone instrument at the substation A. This path extends from the ungrounded terminal of the grounded winding of a busy tone current transformer, not shown, to the busy tone conductor C278, and by way of the contact springs 266 and 268, the lower winding of R210, RC249', RA248 and C217 to the finder switch 182, and through the receiver included in the bridge across the calling line 101, the finder switch 182, C215, RA241, RC242 and the upper winding of R210 to grounded battery. The resulting busy tone indicates to the calling subscriber that the desired connection can not immediately be completed.

The calling subscriber, upon receiving busy tone, may initiate the release of the operated switch train by restoring his receiver to its hook to open the loop circuit over which the line relay R210 is held operated. This relay, upon restoring, interrupts, at RA211 and RC212, the operating circuit of the hold relay R220 and prepares, at RA211 and RC213, a point in the circuit for energizing the release magnet M262. Shortly thereafter, the hold relay R220 restores and removes ground potential, at RA221, from the release conductor C216, whereupon the first selector switch 100 and the operated finder switch 182 are restored to their idle positions and the operated relay R170 in the line circuit 180 is restored to its idle position. Also, upon restoring, the hold relay R220 completes, at RA222 and RC224, the circuit for energizing the release magnet M262, this circuit extending from ground at RA247 by way of RA211, RC213, RA222, RC224, the contact springs 272 and 273 of the vertical off-normal springs 269 and the winding of M262 to battery. In response to the energization of the release magnet M262, the wipers of the mechanism 218 are restored to normal, at which time the rotary and vertical off-normal springs 263 and 269, respectively, are returned to normal. Thus, the partially completed connec-

tion is cleared out, and the switches involved therein are released for further use.

Continuing now with the operation of the apparatus to establish a connection to the called line 109 and assuming that the connector switch 300 is selected by the second selector switch 200 to forward the connection, immediately the loop circuit is extended to the connector switch 300, the line relay R320 in this switch is energized.

5 This circuit extends from the grounded release conductor C297 by way of the contact springs 388 and 387 of the vertical off-normal springs 385, the lower winding of R320, RC316, RA314, the line conductor C298 of the trunk line 295, the operated switch train including the second selector switch 200, the first selector switch 100, the finder switch 182 and the bridge across the calling line 101, the operated switch train, the line conductor C296 of the trunk line 295, RA312, RC313 and the upper winding of R320 to battery. Upon operating, the line relay R320 completes, at RA321 and RC322, an obvious circuit for energizing the hold relay R330. The last-mentioned relay in turn operates to complete, at RA331, an obvious path for applying multiple ground potential to the release conductor C297 of the trunk line 295, thereby to hold the switch train operated and to retain ground potential upon the control conductor C107 of the calling line 101 after the hold relay R220 in the second selector switch 200 restores to remove ground at RA221 from the release conductor C216, as previously explained. At RA332, the hold relay R330 prepares a circuit, traced hereinafter, for energizing the switching through relay R380 and, at RA333 and RC334, an impulsing circuit is prepared for energizing in series the control relay R340 and the vertical magnet M390 in accordance with the impulses comprising the third digit dialed at the calling substation A.

40 The impulsing circuit for the control relay R340 and the vertical magnet M390 is completed at the beginning of the first impulse of the third series of impulses dialed at the calling substation A and when the line relay R320 restores, this circuit extending from ground at RA321 by way of RC323, RA333, RC334, the contact springs 398 and 399 of the vertical off-normal springs 393, the winding of R340, and the winding of M390 to battery. When energized over the above-traced circuit, the vertical magnet M390 lifts the wiper carriage structure of the mechanism 399 one step or to a position opposite the first level of bank contacts. Upon operating, the control relay R340 prepares at RA341 and RC342 an alternative impulsing circuit, traced hereinafter, for energizing in series the control relay R340 and the vertical operating magnet M390 and interrupts at RA341 and RC343 a point 45 in the circuit for energizing in parallel the control relay R370 and the rotary magnet M391. Simultaneously with this operation, the vertical off-normal springs 385 are operated to the off-normal position, thereby interrupting at the contact springs 387 and 388 the original operating circuit of the line relay R320 and completing at the contact springs 386 and 387 an alternative circuit for energizing the line relay R320, the latter circuit extending from ground at the contact spring 386 by way of the contact spring 337, the lower winding of R320, RC316, and RA314 to the line conductor C298 of the trunk line 295, through the operated switch train and the bridge, at the substation A across the calling line 101 to the line conductor C296 of the trunk line 295,

5 and from the line conductor C296 by way of RA312, RC313 and the upper winding of R320 to battery. Also, the vertical off-normal springs 393 are moved to the off-normal position, thereby interrupting, at the contact springs 396 and 398, the original impulsing circuit for energizing in series the control relay R340 and the vertical magnet M390, preparing at the contact springs 397 and 399 a point in the alternative impulsing circuit for energizing in series the control relay R340 and the vertical magnet M390, and preparing at the contact springs 394 and 395 a point in a circuit, traced hereinafter, for energizing the release magnet M392. During each impulse of the third series of impulses, the vertical magnet M390 is energized in the above-described manner so that, at the conclusion of the third digit, the wiper carriage structure of the mechanism 399 stands in a position opposite the level of bank contacts at which are terminated the lines of the ten-line group including the called line 109. During the third series of impulses, each time the bridge across the line conductors C102 and C103 at the substation A is interrupted, the line relay R320 restores, causing the control relay R340 and the vertical operating magnet M390 to be energized as previously explained. After the first impulse the circuit for energizing in series the control relay R340 and the vertical magnet M390 extends from ground 20 at RA321 by way of RC323, RA333, RC334, the contact springs 398 and 397, RA341, RC342, the winding of R340 and the winding of M390 to battery. Also, each time the bridge across the line conductors C102 and C103 at the substation A 25 is completed, the line relay R320 reoperates and completes the energizing circuit of the hold relay R330. Thus, the hold relay R330 and the control relay R340 remain operated during the impulsing, due to their slow-to-release characteristics. 30

35 With the wiper carriage structure of the switch mechanism 399 standing opposite the level of bank contacts at which are terminated the lines of the ten-line group including the called line 109, 45 the connector switch is conditioned to rotate the wipers step by step in accordance with the impulses comprising the fourth and final digit dialed at the calling substation. Thus, shortly following the end of the third series of impulses, the control relay R340 restores to interrupt, at RA341 and RC342, the alternative impulsing circuit for energizing in series the control relay R340 and the vertical magnet M390 and prepares, at RA341 and RC343, a circuit, traced hereinafter, for 50 energizing in parallel the control relay R370 and the rotary magnet M391. At the beginning of the first impulse of the fourth series of impulses dialed at the calling substation A and when the line relay R320 restores, the impulsing circuit 55 for energizing in parallel the control relay R370 and the rotary magnet M391 is completed, this circuit extending from ground at RA321 by way of RC323, RA333, RC334, the contact springs 398 and 397, RA341, RC343, and RA364 to RA383, 60 where the circuit is divided, one branch extending through the winding of R370 to battery and the other branch extending through the winding of M391 to battery. When energized over the above-traced circuit, the control relay R370 65 interrupts, at RA371 and RC373, a point in a circuit, traced hereinafter, for energizing the switching-through relay R380, completes, at RA371 and RA372, a point in a circuit, traced hereinafter, for testing the idle or busy condi- 70 75

tion of the called line 109, and completes, at RA375, a path in the circuit for energizing in parallel the control relay R370 and the rotary magnet M391 short-circuiting the contact controlled by the armature RA364 of the busy relay R360. When the rotary magnet M391 is energized over the above-traced circuit, the wipers of the mechanism 399 are rotated into engagement with the contacts of the first contact set 10 in the level of contact sets at which the called line 109 terminates. The control relay R370 and the rotary magnet M391 are repeatedly energized over the above-traced circuit in accordance with the series of impulses comprising the fourth digit 15 dialed at the substation A, whereupon the wipers of the mechanism 399 engage the contact set in the previously selected level at which the called line 109 terminates. At this time the wipers 376, 377 and 378 of the mechanism 399 engage the contacts 317, 318 and 319, respectively, at which the conductors C110, C115 and C112, respectively, of the called line 109 terminate. The line comprising the conductors C110, C115 and C112 also constitutes a connecting line, the 20 line conductor C110 and C112 thereof being associated in the line circuit 181 with the line conductor C110 and C111 of the subscriber line 109 in a manner more fully explained below.

In the event the called line 109 is busy, ground 25 potential appears upon the control conductor C115 thereof, whereupon the busy relay R360 is energized, this circuit extending from the grounded control conductor C115 of the called line 109 by way of the contact 318, the wiper 377, the conductor C368, RA371, RA372, and the winding of R360 to battery. When energized over the above-traced circuit, the busy relay R360 operates to interrupt, at RA361 and RC362, a point in the circuit for energizing the switching-through relay R380 and prepares, at RA361 and RC363, a point in a circuit, traced herein-after, for locking the busy relay R360 in operated position. Also, the busy relay R360 interrupts, at RA364, a point in the original impulse 30 circuit for energizing in parallel the control relay R370 and the rotary magnet M391 and completes, at RA365 and RC366, a circuit for returning busy tone current to the calling substation A. The latter circuit extends from pulsating ground upon the busy conductor C366' by way of RC366, RA365, C348, the voice coupling condenser 346, to the line conductor C298 of the trunk line 295, from the line conductor C298 through the operated switch train, the bridge 35 including the receiver of the telephone instrument across to calling line 101 at the calling substation A and back through the operated switch train to the line conductor C296 of the trunk line 295, and from the line conductor C296 by way of the voice coupling condenser 345, C347 and the upper winding of R310 to battery. Shortly following the termination of the fourth series of impulses, the control relay R370 restores, due to its slow-to-release characteristic, and completes, at RA372 and RC374, a locking circuit for the busy relay R360, this circuit extending from ground at RA332 by way of RA361, RC363, RC374, RA372 and the winding of R360 to battery. Upon restoring, the control relay R370 also completes, at RA371 and RC373, a point in the circuit, traced herein-after, for energizing the switch-through relay R380, this circuit being interrupted, at RA361 and RC362, at this time. The resulting busy tone indicates to the calling subscriber that

the desired connection cannot immediately be completed.

In the event that the called line 109 is idle, battery potential appears upon the control conductor C115, this battery potential being derived at the intermediate winding of the combined line and two-step cut-off relay R165 in the line circuit 181 individual to the called line 109, causing the busy relay to be short-circuited and causing the switching-through relay R380 to be energized, after the control relay R370 restores. The circuit for energizing R380 extends from ground at RA332 by way of RA361, RC362, the upper winding of R380, RC373, RA371, the conductor C368, the wiper 377, the contact 318, the control conductor C115 of the called line 109 and the intermediate winding of the combined line and cut-off relay R165 in the line circuit 181 to battery. When energized over the above-traced circuit, the switching-through relay R380 operates and prepares, at RA389 and RA384, a circuit for projecting ringing current over the called line to the called substation B, thereby to operate the ringer disposed thereat, completes, at RA382, a locking circuit for itself extending from the grounded release conductor C297 by way of RA382 and the lower winding of R380 to battery, and interrupts, at RA383, a point in the impulsing circuit for energizing in parallel the control relay R370 and the rotary magnet M391. Also, when the switching-through relay R380 operates, it completes, at RA381, a circuit for fully energizing the combined line and two-step cut-off relay R165 in the line circuit 181 individual to the called line 109, the original 35 energizing circuit of the switching-through relay R380 and including the intermediate winding of the relay R165 being ineffective to cause operation of the relay R165, due to the high series resistance of this circuit. The above-men- 40 tioned circuit for fully energizing the relay R165 extends from ground at RA381 by way of the conductor C368, the wiper 377, the contact 318, the control conductor C115 of the called line 109 and the intermediate winding of R165 to 45 battery. When the relay R165 is energized over the last-mentioned circuit, it fully operates to interrupt, at RA166 and RA167, the connections between the upper and lower windings, respectively, thereof and the line conductors C110 and C111 of the called line 109. Also, the relay R165 completes, at RA168, a point in the circuit for projecting ringing current over the called line 109 to the substation B. This circuit extends from pulsating ground on the ringing conductor C357' by way of RC357, RA355, the conductor C348', RA384, the conductor C369, the wiper 378, the contact 319, the line conductor C112, RA168, the line conductor C111, the ringer bridged across the line conductors C111 and C110 50 of the called line 109 at the called substation B, the line conductor C110, the contact 317, the wiper 376, the conductor C367, RA389, the conductor C347', RA351, RC352 and the upper winding of the ring cut-off relay R350 to battery. 55 When the ringer is energized over the above-traced circuit, the called party is given an audible signal that the substation B is being called. A portion of this current is returned through the condenser 355' and the voice coupling con- 60 densers 345 and 346 over the loop extending to the calling substation A, in order to indicate to the calling party that the called substation B is being rung. The relay R165 also completes, at RA169, a point in a circuit for marking the called 65 70 75

line 109 as busy in the group of finder switches including the finder switch 182 and interrupts, at RA164, a point in a circuit extending by way of the distributor start conductor C177 for causing the distributor 183 to operate, thereby preventing an idle finder-selector link from being assigned to the called substation B when the substation B is called.

When the call is answered at the called substation B by removing the receiver of the telephone instrument thereat from its associated hook, a low resistance circuit is completed for energizing the ring cut-off relay R350, this circuit being the same as the circuit for projecting ringing current to the substation B, except for the low resistance path bridged across the line conductors C110 and C111 of the called line 109 at the substation B in parallel with the ringer thereat. Shortly thereafter, the ring cut-off relay R350, being of the slow-to-operate type, is operated to interrupt, at RA355 and RC357, the circuit for projecting ringing current to the called substation B; to complete, at RA354, a locking circuit for itself extending from the grounded release conductor C297 by way of RA354, and the lower winding of R350 to battery; to interrupt, at RA351 and RC352 and at RA355 and RC357, the original operating circuit of R350; and to complete, at RA351 and RC353 and at RA355 and RC356, a loop circuit extending to the called substation B. When the loop circuit is extended to the called substation B, the battery reversing relay R310 is energized, this circuit extending from ground at the upper terminal of the lower winding of R310 by way of the lower winding of R310 to the line conductor C348 and from the line conductor C348 by way of RC356, RA355, C348', RA384, C369, the wiper 378, and the contact 319 to the line conductor C112 of the called line 109, through the telephone instrument bridged across the line conductors of the line 109 at the substation B to the line conductor C110 of the called line 109, and from the line conductor C110 by way of the contact 317, the wiper 376, C367, RA389, C347', RA351, RC353, the line conductor C347 and the upper winding of R310 to battery. When energized over the above-traced circuit, the battery reversing relay R310 operates to reverse the battery applied to the line conductors C296 and C298 of the trunk line 295 extending by way of the operated switch train to the calling substation A, this circuit extending from ground at the contact spring 386 of the vertical off-normal springs 385 by way of the contact spring 387, the lower winding of R320, RA311, and RA312 to the line conductor C296, from the line conductor C296 through the operated switch train and the telephone instrument at the calling substation A to the line conductor C298, and from the line conductor C298 by way of RA314, RA315 and the upper winding of R320 to battery. This reversal of battery potential as applied to the line conductors C296 and C298 of the trunk line 295 extending by way of the operated switch train to the calling substation A may be utilized to operate a register, coin collecting device, etc., associated with the calling substation A.

At this time, talking battery is supplied to the loop extending to the calling substation A through the windings of the line relay R320 in the connector switch 300 and talking battery is supplied to the loop extending to the called substation B through the windings of the battery reversing relay R310. Moreover, the loop ex-

tending to the calling substation A and the loop extending to the called substation B are connected for communication therebetween by the voice coupling condensers 345 and 346 interposed, respectively, between the line conductors C296 and C347 and the line conductors C298 and C348.

The release of the established connection including the operated switch train is under the control of the calling party. In releasing the established connection, the calling party replaces the receiver of the telephone instrument at the substation A upon its associated hook, thereby interrupting the loop extending from the substation A and including the line relay R320. When this loop is interrupted, the line relay R320 restores to interrupt, at RA321 and RC322, the operating circuit of the hold relay R330, and to prepare, at RA321 and RC323, a point in a circuit, traced hereinafter, for energizing the release magnet M392. Shortly thereafter, the hold relay R330 restores and interrupts, at RA331, the path for applying ground potential to the release conductor C297 of the trunk line 295, and completes, at RA333 and RC335, the circuit for energizing the release magnet M392, the latter circuit extending from ground at RA321 by way of RC323, RA333, RC335, the contact springs 393 and 394 of the vertical off-normal springs 393 and the winding of M392 to battery. When the release magnet M392 is energized over the above-traced circuit, the wiper carriage structure of the mechanism 399 is returned to normal, thereby moving the vertical off-normal springs 393 into normal position. When the vertical off-normal springs 393 are moved into normal position, the circuit for energizing the release magnet M392 is interrupted at the contact springs 394 and 395. When the wiper carriage structure mechanism 399 is returned to normal position, the wipers 376, 377 and 378 disengage the contacts 317, 318 and 319, respectively, thereby interrupting the loop extending to the called substation B. When the loop extending to the called substation B is interrupted, the operating circuit of the battery reversing relay R310 is interrupted, causing R310 to restore. When ground potential is removed from the release conductor C297, the locking circuit for the switching through relay R380 and the locking circuit for the ring cut-off relay R350 are interrupted, causing these relays to restore. At this time, the connector switch 300 is completely released.

Also, when the loop extending to the called substation B is interrupted, the circuit for energizing the relay R165 is interrupted, causing this relay to restore. The removal of ground potential from the release conductor C297 simultaneously removes ground from the release conductor C216 and C126 connected thereto. When ground potential is removed from the release conductor C216, the circuit for energizing in series the control relay R250 and the switching through relay R240 in the second selector switch 200 is interrupted, causing the relay R240 to release. Upon restoring, the switching through relay R240 completes, at RA247, the circuit for energizing the release magnet M262, this circuit extending from ground at RA247 by way of RA211, RC213, RA222, RC224, the contact springs 272 and 273 of the vertical off-normal springs 269, and the winding of M262 to battery. When the release magnet M262 is energized over the above-traced circuit, the wiper carriage structure of the mechanism 218 is restored to normal posi-

- tion, causing the vertical off-normal springs 269 to be returned to normal position in order to interrupt, at the contact springs 272 and 273, the circuit for energizing the release magnet M262.
- 5 At this time, the second selector switch 200 is completely released. When ground is removed from the release conductor C126, the circuit for energizing in series the control relay R160 and the switching through relay R150 in the first selector switch 100 is interrupted, causing the relay R150 to restore. Upon restoring, the switching through relay R150 completes, at RA157, a circuit for energizing the release magnet M186, this circuit extending from ground at RA157 by way of RA121, RC123, RA132, RC134, the contact springs 195 and 196 of the vertical off-normal springs 197 and the winding of M186 to battery. When the release magnet M186 is energized over the above-traced circuit, 20 the wiper carriage structure of the mechanism 129 is returned to normal position, causing the vertical off-normal springs 197 to be returned to normal position to interrupt, at the contact springs 195 and 196, the circuit for energizing the release magnet M186. At this time the first selector switch 100 is completely released. Also, when ground potential is removed from the release conductor C126, the finder switch 182 is released and the circuit for energizing the relay 25 R170 in the line circuit 180 is interrupted, causing the relay R170 to restore, in order to release the line circuit 180. At this time the established connection between the calling substation A and the called substation B is completely cleared out 30 and all of the equipment included therein is in readiness for further use.
- In accordance with one feature of the invention and as pointed out above, each of the line circuits is connected and arranged to prevent 35 the presence of a potential difference between the contacts in the contact sets in the contact banks of the Strowger finder and connector switches terminating the subscriber line individual to the line circuit when the associated substation is idle. Specifically, the line circuit 181 40 is connected and arranged to prevent the presence of potential difference between the contacts in the contact sets in the contact banks of the finder and connector switches 182 and 300, respectively, terminating the subscriber line 109 individual to the line circuit 181 when the associated substation B is idle. The connection and arrangement of the line circuit 181 will best be understood from the description of the operation 45 thereof appearing hereinafter, while an understanding of the operation of the improved line circuit 181 will be facilitated by considering the arrangement and operation of a conventional line circuit of this type. In a telephone system 50 of the form illustrated in Figs. 1, 2 and 3, utilizing a conventional line circuit of this type, the line conductor C111 of the subscriber line 109 would be connected rigidly to the line conductor C112 thereof. Thus, when the substation B is idle, 55 ground potential would be present upon the line conductor C112, this path extending from ground at the upper terminal of the lower winding of the relay R165 by way of RA167 to the line conductor C112; and the negative potential of 60 grounded battery would be present upon the line conductor C110 of the subscriber line 109, this path extending from the negative terminal of the intermediate winding of the relay R165 by way of RA168 to the line conductor C110. 65
- 70
- 75

C115, the upper winding of R165 and RA166 to the line conductor C110. Hence, a potential difference would be present between the contacts to which the line conductors C110 and C112 are respectively connected in the contact sets in the contact banks in the finder and connector switches 182 and 300, respectively, terminating the subscriber line 109 individual to the line circuit 181 when the associated substation B is idle. In a similar manner, a potential difference would be present between the contacts in the contact sets in the multiplied contact banks of the other finder and connector switches in the groups including the finder and connector switches 182 and 300, respectively. Likewise, a potential difference would be present between the contacts in the contact sets in the contact banks in all of the finder and connector switches terminating idle subscriber lines.

On the other hand, in a telephone system of 20 the form illustrated in Figs. 1, 2 and 3, utilizing the improved line circuit 181, the line conductor C111 of the subscriber line 109 is normally disconnected from the line conductor C112 thereof and is connected thereto by the contacts associated with the armature RA168 of the relay R165 included in the line circuit 181 only when the substation B is busy. Thus, when the substation B is idle, no potential whatever is present upon the line conductor C112 as the armature RA168 of the relay R165 occupies a restored position; and only negative potential of grounded battery appears upon the line conductor C110 of the subscriber line 109, this path extending from the negative terminal of grounded battery 30 at the lower terminal of the intermediate winding of R165 by way of the intermediate winding of R165, the control conductor C115, the upper winding of R165, and RA166 to the line conductor C110. Hence, no potential difference whatever 35 is present between the contacts to which the line conductors C110 and C112 are respectively connected in the contact sets in the contact banks in the finder and connector switches 182 and 300, respectively, terminating the subscriber line 40 109 individual to the line circuit 181, when the associated substation B is idle. Accordingly, when improved line circuits of the form of that indicated at 181 are utilized in a telephone system 45 of this character, a potential difference appears 50 between the contacts in the contact sets in the contact banks in the finder and connector switches only when a substation is busy, at which time the potential difference between the contacts mentioned is desirable in order to accomplish the functions of the apparatus included in the telephone system in the manner described 55 above.

In accordance with another feature of the invention, each of the second selector switches 60 is connected and arranged to prevent the presence of a potential difference between the contacts in the contact sets in the contact banks of the preceding Strowger switches to which the switch is connected, when the switch occupies an idle 65 position. Specifically, the second selector switch 200 is connected and arranged to prevent the presence of a potential difference between the contacts in the contact set in the contact bank of the first selected switch 100, when the second 70 selector switch 200 occupies an idle position. The connection and arrangement of the second selector switch 200 will best be understood from the description of the operation thereof, appearing hereinafter, while an understanding of the 75

operation of the improved second selector switch 200 will be facilitated by considering the arrangement and operation of a conventional second selector switch of this type. In a telephone system of the form illustrated in Figs. 1, 2 and 3, utilizing a conventional second selector switch of this type, the lower terminal of the lower winding of the line relay R210 would be connected directly to ground, this path extending from ground at the lower terminal of the lower winding of R210 by way of the lower winding of R210, RC249' and RA248 to the line conductor C217 of the trunk line 214; and the lower terminal of the upper winding of the line relay R210 would be connected to the line conductor C215 of the trunk line 214, this path extending from the negative terminal of grounded battery at the upper terminal of the upper winding of R210 by way of the upper winding of R210, RC242 and RA241 to the line conductor C215. Hence, a potential difference would be present between the contacts in the contact set in the contact bank of the first selector switch 100 to which the trunk line 214 is connected when the conventional second selector switch occupies an idle position.

On the other hand, in a telephone system of the form illustrated in Figs. 1, 2 and 3, utilizing the improved second selector switch 200, the lower terminal of the lower winding of the line relay R210 is connected to the release conductor C216 of the trunk line 214, instead of being connected directly to ground, this path extending from the lower terminal of the lower winding of the line relay R210 by way of the contact springs 268 and 267 of the rotary off-normal springs 263 and the contact springs 275 and 274 of the vertical off-normal springs 269 to the release conductor C216 of the trunk line 214. Thus, when the improved second selector switch 200 occupies an idle position, no potential whatever is present upon the line conductor C217 and the release conductor C216, and the negative potential of grounded battery is present upon the line conductor C215. Hence, no potential difference is present between the contacts in the contact set in the contact bank of the first selector switch 100 terminating the trunk line 214 when the second selector switch 200 occupies an idle position. Accordingly, when improved second selector switches of the form of that indicated at 200 are utilized in a telephone system of this character, a potential difference is present between the contacts in the contact sets in the bank contacts of the first selector switches only when the second selector switches occupy operated positions, at which time the potential is desirable in order to accomplish the functions of the second selector switches in the manner described above.

In accordance with another feature of the invention each of the connector switches is connected and arranged to prevent the presence of a potential difference between the contacts in the contact sets of the contact banks in the preceding Strowger switches to which the switch is connected, when the switch occupies an idle position. Specifically, the connector switch 300 is connected and arranged to prevent the presence of a potential difference between the contacts in the contact set in the contact bank of the second selector switch 200, when the connector switch 300 occupies an idle position. The connection and arrangement of the connector switch 300 will best be understood from the description of the operation thereof, appearing hereinafter, while an understanding of the operation of the improved con-

nector switch 300 will be facilitated by considering the arrangement and operation of a conventional connector switch of this type. In a telephone system of the form illustrated in Figs. 1, 2 and 3 utilizing a conventional connector switch of this type, the upper terminal of the lower winding of the line relay R320 would be connected directly to ground, thereby connecting ground potential to the line conductor C298 of the trunk line 295, this path extending from ground at the upper terminal of the lower winding of R320 by way of the lower winding of R320, RC316 and RA314 to the line conductor C298; and battery at the lower terminal of the upper winding of R320 would be connected by way of the upper winding of R320, RC313 and RA312 to the line conductor C296 of the trunk line 295. Hence a potential difference would be present between the contacts in the contact set in the contact bank of the second selector switch 200 to which the trunk line 295 is connected, when the conventional connector switch occupies an idle position.

On the other hand, in a telephone system of the form illustrated in Figs. 1, 2 and 3 utilizing the improved connector switch 300, the upper terminal of the lower winding of the line relay R320 is connected to the release conductor C297 by way of the contact springs 388 and 387 of the vertical off-normal springs 385, instead of being connected directly to ground, when the connector switch 300 occupies an idle position. Also the vertical off-normal springs 385 include a contact spring 386 which cooperates with the contact spring 387 to apply ground potential at the contact spring 386 to the upper terminal of the lower winding of the line relay R320, when the connector switch 300 occupies an operated position. Thus, when the improved connector switch 300 occupies an idle position no potential whatever is present upon the line conductor C298 and the release conductor C297, and the negative potential of grounded battery is present upon the line conductor C296. Hence, no potential difference is present between the contacts in the contact set in the contact bank of the second selector switch 200 terminating the trunk line 295, when the connector switch 300 occupies an idle position. Accordingly, when improved connector switches of the form of that indicated at 300 are utilized in a telephone system of this character, a potential difference is present between the contacts in the contact sets in the contact banks of the second selector switches only when the connector switches occupy operated positions, at which time the potential is desirable in order to accomplish the functions of the connector switches in the manner described above.

In accordance with further features of the invention each of the line circuits and each of the second selector switches is connected and arranged to prevent hunting of the cut-off relay in the line circuit and certain of the relays embodied in the second selector switch of an operated switch train during the release of the switch train. It will be understood that the connection and arrangement of the improved line circuits and the improved second selector switches constitute independent means for preventing the hunting of the relays noted, and only one of these means is required in order to eliminate the hunting of the relays. Specifically, the improved line circuit 180 is connected and arranged to prevent the hunting of the cut-off relay R170 therein and certain of the relays in the second selector switch 200, and the improved second selector switch 200 is con-

structed and arranged to prevent the hunting of the cut-off relay R170 in the line circuit 180 and certain of the relays in the second selector switch 200. The connection and arrangement of the line circuit 180 and the second selector switch 200 will best be understood from a consideration of the operation thereof during the release of the switch train, appearing hereinafter, while an understanding of the operation of the improved line circuit 180 and the improved second selector switch 200 will be facilitated by considering the arrangement and operation of a telephone system of this type including a reconstructed line circuit and a reconstructed second selector switch of the general types of the line circuit 180 and the second selector switch 200, which reconstructed line circuit and second selector switch are not provided with the previously mentioned means for preventing hunting of the relays noted. In a telephone system of the form illustrated in Figs. 1, 2 and 3 utilizing a reconstructed line circuit similar to the line circuit 180, wherein the line conductor C103 of the subscriber line 101 is directly connected to the line conductor C104; and a reconstructed second selector switch similar to the second selector switch 200 wherein the lower terminal of the lower winding of the line relay R210 is connected to the release conductor C216 of the trunk line 214 only by way of the contact springs 268, 267 and 264 of the rotary off-normal springs 263 and not including the contact springs 274 and 275 in the vertical off-normal springs 269 and the contacts controlled by the armature RA225 of the hold relay R220, hunting of the relays noted frequently appears, when the switch train is released.

Assuming that in this telephone system of the general form illustrated in Figs. 1, 2 and 3 and embodying apparatus reconstructed in the manner set forth above, a call has been initiated at the substation A and the first digit has been dialed, causing the finder switch 182, the first selector switch 100 and the second selector switch 200 to be seized and that the switch train is then released by replacing the receiver of the telephone instrument upon its associated hook at the substation A, the loop extending from the substation A and including the line relay R210 in the second selector switch 200 is first interrupted, causing R210 to restore. Upon restoring the line relay R210 interrupts at RA211 and RC212 the circuit for energizing the hold relay R220 and completes at RA211 and RC213 the circuit for energizing in series the control relay R230 and the vertical magnet M260. The vertical magnet M260 moves the wiper carriage structure of the mechanism 218 in the second selector switch 200 one step in the vertical direction, and the control relay R230 operates to complete at RA231 and RA233 the circuit for energizing the control relay R250, this latter circuit extending from ground at RA221 by way of RA233, RA231, the contact springs 270 and 271 of the vertical off-normal springs 269 and the winding of R250 to battery. Also the control relay R230 completes at RA231 and RA233 a path for short-circuiting the switching through relay R240, this path extending from ground at RA221 by way of RA233, RA231, 261', the winding of R240, the contact springs 265 and 264 of the rotary off-normal springs 263 to the grounded release conductor C216 thereby causing the switching through relay R240 to remain restored. The hold relay R220, being of the slow-to-release type, restores shortly after the line relay R210 and removes ground potential at RA221 from the release conductor C216, causing the control relay

R250 to restore. Upon restoring the hold relay R220 also interrupts at RA222 and RC223 the circuit for energizing in series the control relay R230 and the vertical magnet M260; the control relay R230 being of the slow-to-release type does not restore at this time. Simultaneously, ground potential is removed from the release conductor C126 connected by way of RC156, RA154, C136, the wiper 118 and the contact 145 to the release conductor C216, from the control conductor C105 connected by way of the finder switch 182 to the release conductor C126, and from the control conductor C107 of the subscriber line 101 connected by way of RA174 to the control conductor C105.

When ground potential is removed from the release conductors C216 and C126 and from the control conductors C105 and C107, the switching through relay R150 in the first selector switch 100, and the cut-off relay R170 in the line circuit 180 tend to restore, and the finder switch 182 tends to release. Now suppose that the cut-off relay R170 is fast to restore, the switching through relay R150 is relatively slow to restore, and the finder switch 182 is relatively slow to release. Thus, the cut-off relay R170 is first to restore and upon restoring connects ground potential at RA172 to the line conductor C104 of the subscriber line 101, this path extending from ground at the upper terminal of the lower winding of R170 by way of the winding of R170 and RA172 to the line conductor C104. This ground potential is fed forward through the finder switch 182 to the line conductor C127 of the trunk line 214 and therefrom by way of RA158, RC159, C131, the wiper 119, the contact 146, the line conductor C217 of the trunk line 214, RA248, RC249', the lower winding of R210, the contact springs 268, 267 and 264 of the rotary off-normal springs 263 to the release conductor C216. This ground potential on the release conductor C216 feeds forward by way of RA233, RA231, the contact springs 270 and 271 of the vertical off-normal springs 269 and the winding of R250 to battery. Hence, the lower winding of R170, the lower winding of R210 and the winding of R250 are energized in series relation. Due to the relatively high resistance of this series circuit the control relay R250 is not operated and the cut-off relay R170 is only partially operated, but the line relay R210 is fully operated.

Also, this ground potential on the release conductor C216 feeds back by way of the contact 145, the wiper 118, C136, RA154 and RC156 to the release conductor C126, and therefrom by way of the contact springs 188 and 189 of the rotary off-normal springs 187, the winding of R150, 185', the contact springs 193 and 194 of the vertical off-normal springs 197 and the winding of R160 to battery. At this time the switching-through relay R150 in the first selector switch 100 is in its operated position due to the fact that this relay is relatively slow to restore, as previously assumed. The switching-through relay R150 and the control relay R160 receive sufficient energization over the above traced circuit to retain the relay R150 in its operated position.

When the line relay R210 is operated over the series circuit previously traced, it completes at RA211 and RC212 the circuit for energizing the hold relay R220, which latter relay operates to apply ground potential at RA221 to the release conductor C216 to completely energize the relays R150 and R160 in series thereby to prevent the release of the first selector switch 100. The application of ground potential to the release con-

ductor C216 also prevents the release of the finder switch 182 and completely energizes the cut-off relay R170, causing the latter relay to operate. Upon operating the cut-off relay R170 interrupts at RA172 the path for applying ground potential to the line conductor C104 of the subscriber line 101, thereby interrupting the above traced series circuit for energizing the lower winding of R170, the lower winding of R210 and the winding of R250, causing R210 to restore. Shortly thereafter R220 restores and removes at RA221 ground potential from the release conductor C216.

Now, if the cut-off relay R170 is fast to restore, the switching through relay R150 is relatively slow to restore, and the finder switch 182 is relatively slow to release, as previously assumed, the cycle above described will be repeated. Thus the cut-off relay R170 in the line circuit 180 and the relays noted in the second selector switch 200 continue to hunt, causing the switch train to fail to release for further use, in spite of the fact that the substation A is idle.

In the telephone system illustrated in Figs. 1, 2 and 3 embodying the improved line circuit 180, one means for preventing the hunting of the cut-off relay R170 in the line circuit 180 and the relays noted in the second selector switch 200 comprises an arrangement including an armature RA173 provided on the cut-off relay R170 and adapted to control contacts for connecting together the line conductors C103 and C104 of the subscriber line 101. It is noted that the line conductor C103 is normally disconnected from the line conductor C104 and is connected thereto by the contacts controlled by the armature RA173 only when the cut-off relay R170 is fully operated. Thus in the improved line circuit 182 the hunting of the cut-off relay R170 and the relays noted in the second selector switch 200 is positively prevented as ground potential is not present on the line conductor C104 after the cut-off relay R170 restores. Accordingly the previously traced series circuit extending from ground at the upper terminal of the lower winding of R170 to battery at the upper terminal of the winding of R250 and including the lower winding of R170, the lower winding of R210 and the winding of R250 is not completed when the cut-off relay R170 restores, regardless of the sequence of restoration of the cut-off relay R170 in the line circuit 180 and the above enumerated relays in the second selector switch 200.

In the telephone system illustrated in Figs. 1, 2 and 3 embodying the improved second selector switch 200 another means for preventing the hunting of the cut-off relay R170 in the line circuit 180 and the relays noted in the second selector switch 200 comprises the contact springs 274 and 275 of the vertical off-normal contact springs 269. It is noted that the lower winding of the line relay R210 is connected across the line conductor C217 and the release conductor C216 of the trunk line 214 by way of RA248, RC249, the lower winding of R210, the contact springs 268 and 267 of the rotary off-normal springs 263 and the contact springs 275 and 274 of the vertical off-normal springs 269 to the release conductor C216, the contact springs 274 and 275 of the vertical off-normal springs 269 constituting a branch path in this connection. Also an armature RA225 is provided on the hold relay R220 which is adapted to control contact springs for short-circuiting the contact springs 274 and 275 of the vertical off-normal springs 269, the contact springs controlled by the armature RA225

constituting a branch path in the previously mentioned connection. Thus, in the improved second selector switch 200, when the line relay R210 restores and completes at RA211 and RC213, the circuit for energizing in series the control relay R230 and the vertical operating magnet M260, the wiper carriage structure of the mechanism 218 is moved one step in the vertical direction, causing the vertical off-normal springs 269 to be moved into off-normal position, thereby interrupting, at 10 the contact springs 274 and 275, one branch path in the connection between the line conductor C217 and the release conductor C216 including the lower winding of R210. The other branch path in this connection is interrupted when the hold relay R220 restores, thereby completely interrupting the previously traced series circuit extending from ground at the upper terminal of the lower winding of R170 to battery at the upper terminal of the winding of R250 and including 20 the lower winding of R170, the lower winding of R210 and the winding of R250. The interruption of this series circuit positively prevents the hunting of the cut-off relay R170 in the line circuit 180 and the relays noted in the second selector 25 switch 200, regardless of the sequence of restoration of the cut-off relay R170 in the line circuit 180 and the relays noted in the second selector switch 200.

Also it will be apparent that in the telephone 30 system of the general form illustrated in Figs. 1, 2 and 3 and embodying apparatus reconstructed in the manner set forth above, the hunting of the relays noted in the manner described may be incident to the release of an 35 established connection between two subscriber lines. For example, assuming that a release operation is performed at the substation A in order to release an established connection including the switches 182, 100, 200 and 300 between the 40 substations A and B and that the switching through relay R240 in the second selector switch 200 restores together with the line relay R170 in the line circuit 180, upon the release of the connector switch 300 and prior to the restoration of the switching through relay R150 in the first selector switch 100 and the release of the finder switch 182 the above traced series operating circuit is completed at RA172, at RA241, RC242, and at RA248 and RC249'. The relays noted 45 hunt in the manner described above to prevent the release of the line circuit 180 and the switches 182, 100 and 200.

In the telephone system in Figs. 1, 2 and 3 embodying either the improved line circuit 180 or 55 the improved second selector switch 200 this hunting of the relays noted incident to the release of an established connection between the substations A and B is positively prevented. The means comprising the contacts controlled by the 60 armature RA173 of the relay R170 in the line circuit 180 prevents the previously noted series operating circuit from being completed by interrupting the path for applying ground potential to the line conductor C104 of the subscriber line 65 101. Also the means comprising the contact springs 274 and 275 of the vertical off-normal springs 269 in the second selector switch 200 prevents the previously noted series operating circuit from being completed as these contact 70 springs are not moved into engagement until the vertical off-normal springs 269 are returned to normal, which does not occur until the mechanism 218 returns the wiper carriage structure to normal position. Before the mechanism 218 75

can return the wiper carriage structure to normal position the switching through relay R150 in the first selector switch 100 restores and the finder switch 182 releases, thereby interrupting further 5 points in the previously noted series operating circuit and completing releasing the remainder of the apparatus involved in establishing the connection between the substations A and B.

In Fig. 4 there is illustrated a modified form 10 400 of the second selector switch which may be substituted in the telephone system illustrated in Figs. 1, 2 and 3 for the second selector switch 200 illustrated in Fig. 2. In general the arrangement of the second selector switch 400 is the 15 same as that of the second selector switch 200; similar elements in these switches are provided with corresponding reference numerals which differ from each other by two hundred. The operations of similar elements are the same, and 20 in the interest of brevity a complete description of the operations thereof is dispensed with. It is noted that when the second selector switch 400 is substituted for the second selector switch 200 the line conductors C415 and C417 and the release conductor C416 of the trunk line 414 are 25 connected respectively to the contacts 144, 146 and 145 in the illustrated set of contacts in the contact bank in the first selector switch 100. Also the contacts 480, 482 and 481 in the contact set in the contact bank in the second selector switch 400 are connected respectively to the line conductors C296 and C298 and the release conductor C297 of the trunk line 295 extending to the connector switch 300.

30 It is noted that the second selector switch 400 is connected and arranged to prevent the presence of a potential difference between the contacts in the contact sets in the contact banks of the preceding Strowger switches to which this switch is connected, when this switch occupies an idle position. Specifically, the second selector switch 400 is connected and arranged to prevent the presence of a potential difference between the contacts in the contact set in the contact bank of the first selector switch 100, when the second selector switch 400 occupies an idle position. This is accomplished by providing the contact springs 496', 497' and 498' in the vertical off-normal springs 469 and including these contact springs in the circuits for energizing the line relay R410 in a manner pointed out more particularly below.

When the second selector switch 400 is seized by the first selector switch 100, the line relay R410 is energized, this circuit extending from the grounded release conductor C416 by way of the contact spring 464 of the rotary off-normal springs 463, the contact springs 497' and 496' of the vertical off-normal springs 469, the contact springs 467 and 468 of the rotary off-normal springs 463, the lower winding of R410, RC449' and RA448 to the line conductor C417, over the loop extending to the calling substation A to the line conductor C415, and from the line conductor C415 by way of RA441, RC442 and the upper winding of R410 to battery. When the wiper carriage structure in the mechanism 418 is moved one step in a vertical direction the vertical off-normal springs 469 are moved to off-normal 65 position, thereby to interrupt at the contact springs 496' and 497' the previously traced circuit for energizing the line relay R410. This movement of the vertical off-normal springs 469 also completes at the contact springs 498' and 496' an alternative circuit for energizing the line

relay R410, this circuit extending from ground at the contact spring 498' by way of the contact spring 496', the contact springs 467 and 468, the lower winding of R410, RC449' and RA448 to the line conductor C417, over the loop extending to the calling substation A to the line conductor C415, and from the line conductor C415 by way of RA441, RC442 and the upper winding of R410 to battery. This arrangement positively prevents the presence of potential difference between the contacts in the contact set in the contact bank of the first selector switch 100 when the second selector switch 400 occupies an idle position, as previously explained. 10

Also it is noted that the second selector switch 15 400 embodies means comprising the contact springs 496' and 497' in the vertical off-normal springs 469 for preventing the hunting of the cut-off relay R170 in the line circuit 180 and the relays in the second selector switch 400 corresponding to the relays noted in the second selector switch 200. As previously pointed out, the series circuit which causes the cut-off relay R170 in the line circuit 180 and the relays noted in the second selector switch 400 to hunt, extends 20 from ground at the upper terminal of the lower winding of R170 to battery at the upper terminal of the control relay R450, and includes the lower winding of R170, the lower winding of R410 and the winding of R450. Specifically, in 25 the second selector switch 400 this series circuit includes a path extending from the line conductor C417 by way of RA448, RC449', the lower winding of R410, the contact springs 468 and 467 of the rotary off-normal springs 463, the contact springs 496' and 497' of the vertical off-normal springs 469 and the contact spring 464 of the rotary off-normal springs 463 to the release conductor C416. However, this path is interrupted at the contact springs 497' and 496' 30 of the vertical off-normal springs 469, when the wiper carriage structure in the mechanism 418 is moved a first step in a vertical direction or occupies a vertical off-normal position, the vertical off-normal springs 469 occupying the off-normal 35 position at this time. Thus this series circuit which causes the line relay R410 to operate is interrupted, thereby positively preventing the hunting of the cut-off relay R170 in the line circuit 180 and the relays noted in the second 40 selector switch 400.

In Fig. 5 there is illustrated another modified form 500 of the second selector switch which may be substituted in the telephone system illustrated in Figs. 1, 2 and 3 for the second selector switch 200 illustrated in Fig. 2. In general the arrangement of the second selector switch 500 is the same as that of the second selector switch 200; similar elements in these switches are provided with corresponding reference numerals 55 60 which differ from each other by three hundred. The operations of similar elements are the same, and in the interest of brevity a complete description of the operation thereof is dispensed with. It is noted that when the second selector switch 500 is substituted for the second selector switch 200 the line conductors C515 and C517 and the release conductor C516 of the trunk line 514 are connected respectively to the contacts 144, 146 and 145 in the illustrated set of contacts in the 65 contact bank in the first selector switch 100. Also the contacts 580, 582 and 581 in the contact set in the contact bank in the second selector switch 500 are connected respectively to the line conductors C296 and C298 and the release con- 70

ductor C297 of the trunk line 295 extending to the connector switch 300.

It is noted that the second selector switch 500 is connected and arranged to prevent the presence of a potential difference between the contacts in the contact sets in the contact banks of the preceding Strowger switches to which this switch is connected, when this switch occupies an idle position. Specifically, the second selector switch 500 is connected and arranged to prevent the presence of a potential difference between the contacts in the contact set in the contact bank of the first selector switch 100, when the second selector switch 500 occupies an idle position. This is accomplished by connecting the lower terminal of the lower winding of the line relay R510 by way of the contact springs 568 and 567 of the rotary off-normal springs 563, a copper oxide rectifier 574 and the contact spring 564 of the rotary off-normal springs 563 to the release conductor C516.

When the second selector switch 500 is seized by the first selector switch 100 the line relay R510 is energized, this circuit extending from the grounded release conductor C516 by way of the contact spring 564 of the rotary off-normal springs 563, the copper oxide rectifier 574, the contact springs 567 and 568 of the rotary off-normal springs 563, the lower winding of R510, RC549' and RA548 to the line conductor C517, over the loop extending to the calling substation A to the line conductor C615, and from the line conductor C615 by way of RA541, RC542 and the upper winding of R510 to battery. This arrangement positively prevents the presence of potential difference between the contacts in the contact set of the contact bank in the first selector switch 100, when the second selector switch 500 occupies an idle position as previously explained.

It is noted that in the circuit for energizing the line relay R510 current flows from the grounded release conductor C516 through the copper oxide rectifier 574 to the contact spring 567 of the rotary off-normal springs 563. This direction of flow of the current through the copper oxide rectifier 574 is in the conducting direction thereof; thus, full energizing current traverses the windings of the line relay R510.

Also it is noted that the second selector switch 500 embodies means comprising the uni-directional conducting device or copper oxide rectifier 574 for preventing the hunting of the cut-off relay R170 in the line circuit 180 and the relays in the second selector switch 500 corresponding to the relays noted in the second selector switch 200. As previously pointed out, the series circuit which causes the cut-off relay R170 in the reconstructed line circuit 180 and the relays noted in the second selector switch 500 to hunt, extends from ground at the upper terminal of the lower winding of R170 to battery at the upper terminal of the control relay R550 and includes the lower winding of R170, the lower winding of R510 and the winding of R550. In this series circuit current flows from ground at the upper terminal of the lower winding of R170 to battery at the upper terminal of the winding of R550. This current flows from the line conductor C517 by way of RA548, RC549', the lower winding of R510, the contact springs of 568 and 567 of the rotary off-normal springs 563, the copper oxide rectifier 574 and the contact spring 564 of the rotary off-normal springs 563 to the release conductor C516. This direction of flow

of the current through the copper oxide rectifier 574 is in the blocking direction thereof; thus, substantially no current will flow through the copper oxide rectifier 574. Accordingly, substantially no current traverses this series circuit to energize the lower winding of the line relay R510 to cause operation thereof. Hence the hunting of the cut-off relay R170 in the line circuit 180 and the relays noted in the second selector switch 500 is positively prevented.

In Fig. 6 there is illustrated a further modified form 600 of the second selector switch which may be substituted in the telephone system illustrated in Figs. 1, 2 and 3 for the second selector switch 200 illustrated in Fig. 2. In general the arrangement of the second selector switch 600 is the same as that of the second selector switch 200; similar elements in these switches are provided with corresponding reference numerals which differ from each other by four hundred. The operations of similar elements are the same, and in the interest of brevity a complete description of the operation thereof is dispensed with. It is noted that when the second selector switch 600 is substituted for the second selector switch 200 the line conductors C615 and C617 and the release conductor C616 of the trunk line 614 are connected respectively to the contacts 144, 146 and 145 in the illustrated set of contacts in the contact bank in the first selector switch 100. Also the contacts 680, 682 and 681 in the contact set in the contact bank in the second selector switch 600 are connected respectively to the line conductors C296 and C298 and the release conductor C297 of the trunk line 295 extending to the connector switch 300.

It is noted that the second selector switch 600 is connected and arranged to prevent the presence of a potential difference between the contacts in the contact sets in the contact bank of the preceding Strowger switches to which this switch is connected, when this switch occupies an idle position. Specifically, the second selector switch 600 is connected and arranged to prevent the presence of a potential difference between the contacts in the contact set in the contact bank of the first selector switch 100, when the second selector switch 600 occupies an idle position. This is accomplished by connecting the lower terminal of the lower winding of R610 by way of the contact springs 668, 667 and 664 of the rotary off-normal springs 663 to the release conductor C616.

When the second selector switch 600 is seized by the first selector switch 100 the line relay R610 is energized, this circuit extending from the grounded release conductor C616 by way of the contact springs 664, 667 and 668 of the rotary off-normal springs 663, the lower winding of R610, RC649', and RA648 to the line conductor C617, over the loop extending to the calling substation A to the line conductor C615, and from the line conductor C615 by way of RA641, RC642 and the upper winding of R610 to battery. This arrangement positively prevents the presence of potential difference between the contacts in the contact set in the contact bank of the first selector switch 100, when the second selector switch 600 occupies an idle position, as previously explained.

Also it is noted that the second selector switch 600 does not embody means for preventing the hunting of the cut-off relay R170 in the line circuit 180 and the relays in the second selector switch 600 corresponding to the previously noted

relays in the second selector switch 200, as it is contemplated that the second selector switch 600 will be utilized in a telephone system of the form illustrated in Figs. 1, 2 and 3 embodying the improved line circuit 180.

In Fig. 7 there is illustrated a modified form 709 of the line circuit which may be substituted in the telephone system illustrated in Figs. 1, 2 and 3 for the line circuits 180 and 181 illustrated 10 in Fig. 1. In brief, the line circuit 709 is individually associated with a subscriber line 700 having a substation C connected thereto and is accessible to a finder switch 710 controlled by a link distributor 712. Preferably the substation 15 C, the finder switch 710 and the distributor 712 correspond, respectively, to the substation A, the finder switch 182 and the distributor 183 previously described in connection with Fig. 1, and the line circuit 709 comprises a line relay 20 R720 and a cut-off relay R730.

Referring now more particularly to the operation of the line circuit 709, when the subscriber at the substation C initiates a call over the line 700 by lifting his receiver from its associated 25 hook, a circuit is completed for energizing the line relay R720. This circuit extends from ground at the lower terminal of the lower winding of R720 by way of RA733, the line conductor C702 of the line 700, the bridge across the line conductors C702 and C701 at the substation C, C701, RA732 and the upper winding of R720 to battery. When energized over the above traced 30 circuit the line relay R720 operates to apply at RA721 ground potential to the distributor start 35 conductor C711 thereby to cause the distributor 712 to initiate the operation of one of the finder switches to search for the calling line 700. At RA722 a path is prepared for applying ground potential to the control conductor C707 of the 40 connecting line 703 extending to the bank contacts of the connector switches at which this line terminates, thereby to mark the line 700 busy. Also, at RA722 battery, as applied to the upper terminal of the winding of the cut-off 45 relay R730, is applied to the control conductor C708 of the link line 704 and extends to the bank contacts of the finder switches terminating the link line 704, thereby to mark the line 700 as the calling line. Assuming, for example, that 50 the finder switch 710 is the switch assigned by the distributor 712 to the use of the line 700, the wipers of this switch are first operated to a position opposite the level in which the link line 704 is terminated, this level being identified 55 through the application of marking or ground potential to the start conductor C711. When this level is found, the wipers are automatically stepped into the bank contact field to test the individual lines terminated at the selected bank 60 contact level. When the link line 704 marked by the application of battery to the control conductor C708 thereof is found, the hunting operation is automatically discontinued and the control apparatus embodied in the finder switch 65 710 functions automatically to switch the link line 704 through and establish a connection between this link line and the trunk line incoming to the first selector switch. Following this operation, the finder switch 710 is marked as 70 busy in the distributor 712 and the distributor is started in operation to a position corresponding to the next available idle finder switch. Also, in the course of these operations, direct ground potential is applied in the finder switch 710 to 75 the control conductor C708, thereby to mark

the calling line 700 as busy through the application of ground potential to the control conductor C707 of the connecting line 703. This application of direct ground potential to the control conductor C708 causes the cut-off relay R730 to be energized, this circuit extending from the grounded control conductor C708 by way of RA722 and the winding of R730 to battery. When energized, the cut-off relay R730 operates to connect the line conductors C701 and C702 of the calling line 700 at RA731 and RA735, respectively, to the line conductors C705 and C706 of the link line 704, interrupts at RA732 and RA733 the operating circuit of the line relay R720, causing the latter relay to restore. Also the cut-off 15 relay R730 interrupts at RA734 the path for applying ground potential to the start conductor C711 and completes at RA736 a holding circuit for itself and a circuit for applying ground potential to the control conductor C707 of the 20 connecting line 703, thereby to mark the calling line 700 busy. Upon restoring, the line relay R720 interrupts at RA721 a further point in the path for applying ground potential to the start conductor C711 and interrupts at RA722 the 25 original operating circuit of the cut-off relay R730. At this time a link connection is completed between the substation C and the first selector switch which is clear of all impedance 30 elements which might interfere with the transmission of impulsing and voice frequency currents. The impulsing device at the substation C may be operated at this time to initiate the operation of the switch train in the usual manner. 35

In releasing the established connections the receiver of the telephone instrument at the substation C is replaced upon its associated hook switch thereby interrupting the loop extending to the switch train to cause the switch train to be released. When the switch train is released, ground potential is removed from the control conductor C708, causing the cut-off relay R730 to restore and interrupt at RA731 and RA735, respectively, the connections between the line conductors C701 and 40 C702 of the line 700 and the line conductors C705 and C706 of the link line 704. Also, upon restoring, the cut-off relay R730 prepares at RA732 and RA733 points in the operating circuit of the line relay R720, prepares at RA734 a point in the 45 path for applying ground potential to the start conductor C711, and interrupts at RA736 a point in its holding circuit. At this time the switch train, the line circuit 709 and the apparatus at the substation C are released and ground potential is removed from the control conductor C707 of the connecting line 703, thereby rendering this apparatus idle for further use. 50

When a call is extended from a connector switch to the substation C ground potential is first applied in the connector switch to the control conductor C707 of the connecting line 703, thereby completing an obvious circuit for energizing the cut-off relay R730. When energized, the cut-off relay R730 operates to connect the line conductors C701 and C702 of the called line 700 at RA731 and RA735, respectively, to the line conductors C705 and C706 of the connecting line 703, thereby to complete a loop between the ringer at the called substation C and the connector switch 70 by way of the called line 700, the link line 704, and the connecting line 703. Upon operating, the cut-off relay R730 also interrupts at RA732 and RA733 points in the operating circuit of the line relay R720, and interrupts at RA734 a point in the path 75

for applying ground potential to the start lead 711, thereby to prevent operation of the distributor 712 to assign a finder switch to the called substation C. The apparatus at the substation 5 C is then in condition to be rung in the usual manner.

It is noted that the line circuit 709 is connected and arranged to prevent the presence of potential between the contacts in the contact sets in 10 the contact banks in the Strowger finder and connector switches terminating the link line 704 and the connecting line 703 and adapted to be connected to the subscriber line 700. This is accomplished by directly connecting the line conductors C705 and C706 of the link line 704 to the corresponding line conductors of the connecting line 703, and by connecting the line conductors C701 and C702 of the subscriber line 700 to the line conductors C705 and C706 of the link line 20 704 at RA731 and RA735, respectively, of the cut-off relay R730. Also, it is noted that the control conductor C708 of the link line 704 is adapted to be connected to the control conductor C707 of the connecting line 703 at RA722 and RA736 of 25 the line relay R720 and the cut-off relay R730, respectively. Thus, when the substation C is idle, the line conductors C701 and C702 of the subscriber line 700 are disconnected at RA731 and RA735, respectively, from the line conductors 30 C705 and C706 of the link line 704 and the connecting line 703, and the control conductor C708 of the link line 704 is disconnected at RA722 of R720 and at RA736 of R730 from the control conductor C707 of the connecting line 703. Only battery connected to the upper terminal of the winding of the cut-off relay R730 is present upon the control conductor C707 of the connecting line 35 703, thereby to mark the calling line 700 as idle in the contact bank of the connector switches 40 having access thereto. Thus, no potentials whatever are present upon the line conductors C705 and C706 and the control conductor C708 of the link line 704 and the line conductors C705 and C706 of the connecting line 703. Accordingly, no 45 potential difference is present between the contacts in the contact sets in the contact banks of the finder and connector switches terminating the subscriber line 700.

Also, it is noted that the line circuit 709 embodies means comprising the contacts controlled by the armature RA735 of the cut-off relay R730 for preventing the hunting of the relays R720 and R730 and the relays hereinbefore noted in the second selector switch. As previously pointed 50 out, the series circuit which causes the relay R170 in the reconstructed line circuit 180 corresponding to the relays R720 and R730 to hunt, extends from ground at the upper terminal of the lower winding of R170 by way of the line conductor of 55 the link line corresponding to the line conductor C706 of the link line 704 to battery at the upper terminal of a control relay in the second selector switch, and includes the lower winding of R170, the lower winding of a first control relay and the 60 winding of another control relay in the second selector switch. In the line circuit 709 this series circuit cannot be completed when the cut-off relay R730 restores as this series circuit is interrupted at RA735. Thus, this series circuit 65 70 which causes the control relay in the second selector switch to operate is interrupted, thereby positively preventing the hunting of the relays R720 and R730 in the line circuit 709 and the control relays noted in the second selector switch.

75 While there have been described what are at

present considered to be the preferred embodiments of the invention, it will be understood that various modifications may be made therein, and it is contemplated to cover in the appended claims all such modifications as fall within the true spirit and scope of the invention.

What is claimed is:

1. In a telephone system comprising an exchange having a first line extending thereto including two line conductors and adapted to have a bridge connected across the line conductors thereof when a call is initiated thereon; a link line including two line conductors, the line conductors of said link line being normally disconnected from the line conductors of said first line, a finder switch having access to said link line, a line circuit associated with said lines and including a relay, an operating circuit for said relay including a source of supply and the line conductors of said first line, said operating circuit being completed immediately a bridge is connected across the line conductors of said first line, means responsive to the operation of said relay for causing said finder switch to search for said link line and to seize said link line, and means included in said line circuit and responsive to the seizure of said link line for connecting the corresponding line conductors of said first line and said link line together.

2. In a telephone system comprising an exchange having a first line extending thereto including two line conductors and adapted to have a bridge connected across the line conductors thereof when a call is initiated thereon; a link line including two line conductors, a finder switch having a set of fixed contacts terminating said link line and a set of movable contacts adapted to engage said set of fixed contacts, thereby to seize said link line, the line conductors of said link line being normally disconnected from the line conductors of said first line, thereby to prevent the presence of a potential difference between the contacts in said set of fixed contacts in said finder switch when said first line is idle, a line circuit associated with said lines and including a relay, an operating circuit for said relay including a source of supply normally connected across the line conductors of said first line, said operating circuit being completed immediately a bridge is connected across the line conductors of said first line, means responsive to the operation of said relay for causing said finder switch to search for said link line and to seize said link line, and means included in said line circuit and responsive to the seizure of said link line for connecting the corresponding line conductors of said first line and said link line together.

3. In a telephone system comprising an exchange having a first line extending thereto including two line conductors and adapted to have a bridge connected across the conductors thereof when a call is initiated thereon; a link line including two line conductors, a finder switch having a set of fixed contacts terminating said link line and a set of movable contacts adapted to engage said set of fixed contacts, thereby to seize said link line, a second line including two line conductors connected to the corresponding line conductors of said link line, a connector switch having a set of fixed contacts terminating said second line and a set of movable contacts adapted to engage said set of fixed contacts, thereby to seize said second line, a line circuit associated with said lines and including a relay, an oper-

ating circuit for said relay including a source of supply normally connected across the line conductors of said first line, the line conductors of said link line being normally disconnected from the line conductors of said first line, thereby to prevent the presence of a potential difference between the contacts in said sets of fixed contacts in said finder and connector switches respectively terminating said link line and said second line when said first line is idle, said operating circuit being completed immediately a bridge is connected across the line conductors of said first line, means responsive to the operation of said relay for causing said finder switch to search for said link line and to seize said link line, and means responsive to the seizure of said link line for connecting the corresponding line conductors of said first line and said link line together.

4. In a telephone system comprising an exchange having a first line extending thereto including at least two conductors and adapted to have a bridge connected across the conductors thereof when a call is initiated thereon; a link line including at least two conductors, at least one of the conductors of said link line being normally disconnected from a corresponding one of the conductors of said first line, a finder switch having access to said link line, a line circuit associated with said lines and including a relay having two operated positions, means for causing the operation of said relay to one of said positions immediately a bridge is connected across the conductors of said first line, means responsive to the operation of said relay to said one position for causing said finder switch to search for said link line and to seize said link line, means for causing the operation of said relay to the other of said positions when said link line is seized, and means responsive to the operation of said relay to said other position for connecting said first line and said link line together.

5. In a telephone system comprising an exchange having a first line extending thereto including at least two conductors and adapted to have a bridge connected across the conductors thereof when a call is initiated thereon; a link line including at least two conductors, a finder switch having a set of fixed contacts terminating 50 said link line and a set of movable contacts adapted to engage said set of fixed contacts, thereby to seize said link line, at least one of the conductors of said link line being normally disconnected from a corresponding one of the conductors of said first line, thereby to prevent the presence of a potential difference between the contacts in said set of fixed contacts in said finder switch when said first line is idle, a line circuit associated with said lines and including a relay 55 having two operated positions, a first circuit including a source of supply normally connected across the conductors of said first line for causing the operation of said relay to one of said positions, a second circuit for causing the operation of said relay to the other of said positions, said first 60 operating circuit being completed immediately a bridge is connected across the conductors of said first line, means responsive to the operation of said relay to said one position for causing said 65 finder switch to search for said link line and to seize said link line, said second operating circuit being completed when said link line is seized, and means responsive to the operation of said relay to said other position for connecting said one conductor of said link line to said corresponding one conductor of said first line, thereby to connect said first line and said link line together.

6. In a telephone system comprising an exchange having a first line extending thereto including at least two conductors and adapted to have a bridge connected across the conductors thereof when a call is initiated thereon; a link line including at least two conductors, a finder 10 switch having a set of fixed contacts terminating said link line and a set of movable contacts adapted to engage said set of fixed contacts, thereby to seize said link line, a second line including at least two conductors connected to the corresponding conductors of said link line, a connector switch having a set of fixed contacts terminating said second line and a set of movable contacts adapted to engage said set of fixed contacts, thereby to seize said second line, at least one of the conductors of said link line being normally disconnected from a corresponding one of the conductors of said first line, thereby to prevent the presence of a potential difference between the contacts in said sets of fixed contacts in said 15 finder and connector switches respectively terminating said link line and said second line when said first-mentioned line is idle, a line circuit associated with said first line and said link line and including a relay having two operated positions, a first circuit including a source of supply normally connected across the conductors of said first line for causing the operation of said relay to one of said positions, a second circuit for causing the operation of said relay to the other of said positions, said first operating circuit being completed immediately a bridge is connected across the conductors of said first line, means responsive to the operation of said relay to said one position for causing said finder switch to search for said link line and to seize said link 20 line, said second operating circuit being completed when said link line is seized, and means responsive to the operation of said relay to said other position for connecting said one conductor of said link line to said corresponding one conductor of said first line, thereby to connect said first line and said link line together.

7. In a telephone system, a selector switch having a fixed contact set and a movable contact set adapted to engage said fixed contact set, each of said contact sets including two line contacts and a control contact; a line including two line conductors and a control conductor terminating at the respective contacts in said fixed contact set; another selector switch connected to said line and including a relay operative to initiate operation of said other selector switch; an operating circuit for said relay including one terminal of a source of supply derived in said other selector switch, a winding of said relay, one of said line conductors, one of said fixed line contacts, a loop extending between said movable line contacts, the other of said fixed line contacts, the other of said line conductors, a connection extending between said other line conductor and said control conductor, said control conductor, said fixed control contact, said movable control contact, and the other terminal of the source of supply derived in said first-mentioned selector switch, whereby no potential difference is present between said fixed line contacts when said other selector switch occupies an idle position; and means for causing said movable contact set to engage said fixed contact set, thereby to complete said operating circuit.

8. In a telephone system, a line including two

line conductors and a control conductor; a selector switch having access to said line; another selector switch connected to said line and including a relay having a winding and being operative to initiate operation of said other selector switch; an operating circuit for said relay including one terminal of a source of supply, a connection between said one supply terminal and one terminal of said winding, a connection between the other 5 terminal of said winding and one of said line conductors, a loop including said first-mentioned selector switch and extending between said one line conductor and the other of said line conductors, a connection between said other line 10 conductor and said control conductor in said other selector switch, and a connection between said control conductor and the other terminal of the source of supply derived in said first-mentioned selector switch, whereby no potential difference is present between said line conductors when said other selector switch occupies an idle 15 position; and means for causing said first-mentioned selector switch to seize said line, thereby to complete said operating circuit.

25 9. In a telephone system, a line including two line conductors and a control conductor; a selector switch having access to said line; another selector switch connected to said line and including a relay having a winding and being operative to initiate operation of said other selector switch; an operating circuit for said relay including one terminal of a source of supply, a connection between said one supply terminal and one terminal of said winding, a connection 30 between the other terminal of said winding and one of said line conductors, a loop including said first-mentioned selector switch and extending between said one line conductor and the other of said line conductors, a connection between 35 said other line conductor and said control conductor in said other selector switch, and a connection between said control conductor and the other terminal of the source of supply derived in said first-mentioned selector switch, whereby no potential difference is present between said line conductors when said other selector switch occupies an idle position; and means for causing said first-mentioned selector switch to seize said line, thereby to complete said operating circuit; and means responsive to the operation of said relay for connecting the other terminal of the source of supply derived in said other selector switch to said control conductor.

40 10. In a telephone system, a first line; a selector switch having access to said first line; a second line; another selector switch connected to said first line and including a relay having two windings and being operative to initiate operation of said other selector switch, said other selector switch including a mechanism having an idle position and operative to select said second line; an operating circuit for said relay including one terminal of a source of supply, a connection between said one supply terminal and a terminal of one of said windings, a connection 45 between the other terminal of said one winding and one of said line conductors, a loop including said first-mentioned selector switch and extending between said one line conductor and the other of said line conductors, a connection between said other line conductor and a terminal of the other of said windings, a connection 50 between the other terminal of said other winding and said control conductor, and a connection between said control conductor and the

other terminal of the source of supply derived in said first-mentioned selector switch, whereby no potential difference is present between said line conductors when said other selector switch occupies an idle position; means for causing said first-mentioned selector switch to seize said first line, thereby to complete said operating circuit; means for causing a predetermined operation of said mechanism; and means responsive to said predetermined operation of said mechanism for connecting the other terminal of the source of supply derived in said other selector switch to said other winding, thereby to complete a holding circuit for said relay.

11. In a telephone system, a first line, a selector switch having access to said first line, a second line, another selector switch connected to said first line and including a relay operative to initiate operation of said other selector switch, said other selector switch including a mechanism having an idle position and operative to select said second line, an operating circuit and a holding circuit for said relay, means for causing said first-mentioned selector switch to seize said first line, means responsive to the seizure of said first line for completing said operating circuit, means responsive to the operation of said relay for completing said holding circuit, means for causing a predetermined operation of said mechanism, and means responsive to said predetermined operation of said mechanism for interrupting said operating circuit.

12. In a telephone system, a first line, a first selector switch having access to said first line, a second line, a second selector switch connected to said first line and including a relay operative to initiate operation of said second selector switch, said second selector switch including a mechanism having an idle position and operative to select said second line, an operating circuit for said relay, means for causing said first selector switch to seize said first line, means responsive to the seizure of said first line for completing said operating circuit, means for interrupting said operating circuit, thereby to cause said relay to restore to release said second selector switch, means responsive to the restoration of said relay for causing a predetermined operation of said mechanism, means responsive to said predetermined operation of said mechanism for interrupting a further point in said operating circuit, and means for restoring said mechanism to its idle position.

13. In a telephone system, a first line, a selector switch having access to said first line, a second line, another selector switch connected to said first line and including a first relay and a second relay operative to initiate operation of said other selector switch, said other selector switch including a mechanism having an idle position and operative to select said second line, an operating circuit and a holding circuit for said first relay, means for causing said first-mentioned selector switch to seize said first line, means responsive to the seizure of said first line for completing said operating circuit, means responsive to the operation of said first relay for causing the operation of said second relay, means responsive to the operation of said second relay for completing said holding circuit, means for interrupting said operating and holding circuits, thereby to cause said first and second relays to restore to release said other selector switch, means responsive to the restoration of said first relay for causing a predetermined operation of

said mechanism, means responsive to said predetermined operation of said mechanism for interrupting a further point in said operating circuit, and means responsive to the restoration of 5 said second relay for interrupting a further point in said holding circuit and for restoring said mechanism to its idle position.

14. In a telephone system, a pair of lines having substations adapted to be connected thereto, 10 a plurality of automatic switches arranged to be connected in tandem to set up a connection between said lines, said switches being so connected and arranged that said connection is adapted to be automatically released in response to release 15 operations performed at one or both of said substations, control elements included in said switches, said control elements being so connected and arranged that certain ones thereof have a tendency to interact incident to the initiation 20 of the release of said connection, thereby to prevent the complete release of the corresponding switches, and means for preventing the interaction of said control elements, whereby said switches are completely released in response to 25 the performance of said release operations.

15. In a telephone system, a pair of lines having substations adapted to be connected thereto, 30 a plurality of automatic switches arranged to be connected in tandem to set up a connection between said lines, said switches being so connected and arranged that said connection is adapted to be automatically released in response to release operations performed at one or both of said substations, control elements included in said 35 switches, said control elements being so connected and arranged that certain ones thereof have a tendency to interact incident to the initiation of the release of said connection, thereby to prevent the complete release of the corresponding switches, and means controlled by a predetermined operation of one of said switches for preventing the interaction of said control elements, whereby said switches are completely released in response to the performance of said 45 release operations.

16. In a telephone system, a pair of lines having substations adapted to be connected thereto, 50 a plurality of automatic switches arranged to be connected in tandem to set up a connection between said lines, said switches being so connected and arranged that said connection is adapted to be automatically released in response to release operations performed at one or both of said substations, control elements included in said 55 switches, said control elements being so connected and arranged that certain ones thereof have a tendency to interact incident to the release of said connection, thereby to prevent the complete release of the corresponding switches, and means responsive to the performance of said release operations for preventing the interaction of said control elements, whereby said switches are completely released in response to the performance of said 65 release operations.

17. In a telephone system, a pair of lines having substations adapted to be connected thereto, 70 line circuits individually associated with said lines, a plurality of automatic switches arranged to be connected in tandem to set up a connection between said lines, said switches being so connected and arranged that said connection is adapted to be automatically released in response to release operations performed at one or both of said substations, control elements included in said line circuits and said switches, said control ele- 70

ments being so connected and arranged that a certain control element in at least one of said line circuits and a certain control element in at least one of said switches have a tendency to interact incident to the initiation of the release 5 of said connection, thereby to prevent the complete release of the corresponding line circuit and switch, and means for preventing the interaction of said control elements, whereby said line circuit and switch are completely released in 10 response to the performance of said release operations.

18. In a telephone system, a pair of lines having substations adapted to be connected thereto, 15 line circuits individually associated with said lines, a plurality of automatic switches arranged to be connected in tandem to set up a connection between said lines, said switches being so connected and arranged that said connection is adapted to be automatically released in response to 20 release operations performed at one or both of said substations, control elements included in said line circuits and said switches, said control elements being so connected and arranged that a certain control element in at least one of said 25 line circuits and a certain control element in at least one of said switches have a tendency to interact incident to the initiation of the release of said connection, thereby to prevent the complete release of the corresponding line circuit 30 and switch, and means controlled by a predetermined operation of one of said switches for preventing the interaction of said control elements, whereby said line circuit and switch are completely released in response to the performance 35 of said release operations.

19. In a telephone system, a pair of lines having substations adapted to be connected thereto, a plurality of automatic switches arranged to be connected in tandem to set up a connection between said lines, said switches being so connected and arranged that said connection is adapted to be automatically released in response to release operations performed at one or both of said substations, control relays included in said switches, said control relays being so connected and arranged that an undesirable operating circuit for certain ones of said control relays tends to be completed incident to the initiation of the release of said connection, thereby to prevent the complete release of the corresponding switches, and means controlled by a predetermined operation of one of said switches for interrupting a point in said undesirable operating circuit, whereby said switches are completely released in response to the performance of said release operations.

20. In a telephone system, a pair of lines having substations adapted to be connected thereto, a plurality of automatic switches arranged to be connected in tandem to set up a connection between said lines, said switches being so connected and arranged that said connection is adapted to be automatically released in response to release operations performed at one or both of said substations, control relays included in said switches, said control relays being so connected and arranged that an undesirable operating circuit for certain ones of said control relays tends to be completed incident to the initiation of the release of said connection, thereby to prevent the complete release of the corresponding switches, and means responsive to the performance of said release operations for interrupting a point in said undesirable operating circuit, whereby said 70

- switches are completely released in response to the performance of said release operations.
21. In a telephone system, a line having a substation adapted to be connected thereto, a line circuit individual to said line, a plurality of automatic switches arranged to be connected in tandem to extend a connection from said line to another line, said line circuit and said switches being so connected and arranged that said line circuit and said switches are adapted to be automatically released in response to a release operation performed at said substation, control relays included in said line circuit and said switches, said control relays being so connected and arranged that an undesirable operating circuit for a certain control relay in said line circuit and a certain control relay in at least one of said switches tends to be completed incident to the initiation of the release of said connection, thereby to prevent the complete release of said line circuit and the corresponding switch, means for causing the control relay in said line circuit to restore when said release operation is performed, and means controlled by the restoration of the control relay in said line circuit for interrupting a point in said undesirable operating circuit, whereby said line circuit and said switch are completely released in response to the performance of said release operation.
22. In a telephone system, a first line having a substation adapted to be connected thereto, a line circuit individual to said first line, a second line, a plurality of automatic switches arranged to be connected in tandem to set up a connection between said lines, one of said switches including a mechanism operative to select said second line, said line circuit and said switches being so connected and arranged that said line circuit and said switches are adapted to be automatically released in response to a release operation performed at said substation, control relays included in said line circuit and said switches, said control relays being so connected and arranged that an undesirable operating circuit for a certain control relay in said line circuit and a certain control relay in said one switch tends to be completed incident to the release of said connection, thereby to prevent the complete release of said line circuit and said one switch, and means controlled by a predetermined operation of said mechanism for interrupting a point in said undesirable operating circuit, whereby said line circuit and said one switch are completely released in response to the performance of said release operation.
23. In a telephone system, a first line having a substation adapted to be connected thereto, a line circuit individual to said first line, a second line, a plurality of automatic switches arranged to be connected in tandem to set up a connection between said lines, one of said switches including a mechanism operative to select said second line, said line circuit and said switches being so connected and arranged that said line circuit and said switches are adapted to be automatically released in response to a release operation performed at said substation, control relays included in said line circuit and said switches, said control relays being so connected and arranged that an undesirable operating circuit for a certain control relay in said line circuit and a certain control relay in said one switch tends to be completed incident to the initiation of the release of said connection, thereby to prevent the complete release of said line circuit and said one switch,
- means responsive to the performance of said release operation for causing a predetermined operation of said mechanism, and means controlled by said predetermined operation of said mechanism for interrupting a point in said undesirable operating circuit, whereby said line circuit and said one switch are completely released in response to the performance of said release operation.
24. In a telephone system, a first line having a substation adapted to be connected thereto, a line circuit individual to said first line, a second line, a plurality of automatic switches arranged to be connected in tandem to set up a connection between said lines, one of said switches including a mechanism having vertical and rotary movements to select said second line, said line circuit and said switches being so connected and arranged that said line circuit and said switches are adapted to be automatically released in response to a release operation performed at said substation, control relays included in said line circuit and said switches, said control relays being so connected and arranged that an undesirable operating circuit for a certain control relay in said line circuit and a certain control relay in said one switch tends to be completed incident to the initiation of the release of said connection, thereby to prevent the complete release of said line circuit and said one switch, and means comprising a set of contact springs included in said undesirable circuit and controlled by the vertical movement of said mechanism for interrupting a point in said undesirable operating circuit, whereby said line circuit and said one switch are completely released in response to the performance of said release operation.
25. In a telephone system, a line having a substation adapted to be connected thereto, a line circuit individual to said line, a plurality of automatic switches arranged to be connected in tandem to extend a connection from said line to another line, said line circuit and said switches being so connected and arranged that said line circuit and said switches are adapted to be automatically released in response to a release operation performed at said substation, control relays included in said line circuit and said switches, said control relays being so connected and arranged that an undesirable circuit tending to cause energization of a certain control relay in said line circuit and a certain control relay in at least one of said switches is completed incident to the initiation of the release of said connection, thereby to prevent the complete release of said line circuit and said one switch, and means including a unidirectional conducting device included in said undesirable circuit for preventing the energization of said certain control relays, whereby said line circuit and said one switch are completely released in response to the performance of said release operation.
26. In a telephone system, a line having a substation adapted to be connected thereto, a line circuit individual to said line, a plurality of automatic switches arranged to be connected in tandem to extend a connection from said line to another line, said line circuit and said switches being so connected and arranged that said line circuit and said switches are adapted to be automatically released in response to a release operation performed at said substation, control relays included in said line circuit and said switches, said control relays being so connected and arranged that an undesirable circuit tending

to cause energization of a certain control relay in said line circuit and a certain control relay in at least one of said switches is completed incident to the initiation of the release of said connection, thereby to prevent the complete release of said line circuit and said one switch, and means for blocking the flow of current in said undesirable circuit to prevent the energization of said certain control relays, whereby said line circuit and said one switch are completely released in response to the performance of said release operation.

27. In a telephone system, a line having a substation adapted to be connected thereto, a line circuit individual to said line, a plurality of automatic switches arranged to be connected in tandem to extend a connection from said line to another line, said line circuit and said switches being so connected and arranged that said line circuit and said switches are adapted to be automatically released in response to a release operation performed at said substation, control relays included in said line circuit and said switches, said control relays being so connected and arranged that an undesirable circuit tending to cause energization of a certain control relay in said line circuit and a certain control relay in at least one of said switches is completed incident to the initiation of the release of said connection, thereby to prevent the complete release of said line circuit and said one switch, and means including a rectifier included in said undesirable circuit for blocking the flow of current therein to prevent the energization of said certain control relays, whereby said line circuit and said one switch are completely released in response to the performance of said release operation.

28. In a telephone system, a line having a substation adapted to be connected thereto, a plurality of automatic switches arranged to be connected in tandem to extend a connection from said line to another line, said switches being so connected and arranged that said switches are adapted to be automatically released in response to a release operation performed at said substation, control relays included in said switches, a certain control relay in one of said switches being operative to initiate operation of said one switch, a first energizing circuit for operating said certain control relay, said control relays being so connected and arranged that an undesirable circuit including a portion common to

said first energizing circuit and tending to cause energization of said certain control relay and a certain control relay in at least another of said switches is completed incident to the initiation of the release of said connection, thereby to prevent the complete release of said one switch and said other switch, and means including a unidirectional conducting device included in the common portion of said circuits for preventing the energization of said certain control relays by way of said undesirable circuit, whereby said one switch and said other switch are completely released in response to the performance of said release operation, said device allowing the energization of said certain control relay by way of said first energizing circuit.

29. In a telephone system, a line having a substation adapted to be connected thereto, a line circuit individual to said line, a plurality of automatic switches arranged to be connected in tandem to extend a connection from said line to another line, said line circuit and said switches being so connected and arranged that said line circuit and said switches are adapted to be automatically released in response to a release operation performed at said substation, control relays included in said line circuit and said switches, a certain control relay in one of said switches being operative to initiate operation of said one switch, a first energizing circuit for operating said control relay, said control relays being so connected and arranged that an undesirable circuit including a portion common to said first energizing circuit and tending to cause energization of said certain control relay and a certain control relay in said line circuit is completed incident to the initiation of the release of said connection, thereby to prevent the complete release of said one switch and said line circuit, and means including a unidirectional conducting device included in the common portion of said circuits for preventing the energization of said certain control relays by way of said undesirable circuit, whereby said one switch and said line circuit are completely released in response to the performance of said release operation, said device allowing the energization of said certain control relay by way of said first energizing circuit.
